UNITED STATES PATENT OFFICE.

EUGENE L. KEYES, OF CHICAGO, ILLINOIS, ASSIGNOR TO UNITED SHOE MACHINERY CORPORATION, OF PATERSON, NEW JERSEY, A CORPORATION OF NEW JERSEY.

HEEL-SEAT LASTING AND NAILING MACHINE.

Application filed December 22, 1917. Serial No. 206,434.

To all whom it may concern:

Be it known that I, EUGENE L. KEYES, a citizen of the United States, residing at Chicago, in the county of Cook and State of Illinois, have invented certain Improvements in Heel-Seat Lasting and Nailing Machines, of which the following description, in connection with the accompanying drawings, is a specification, like reference characters on the drawings indicating like parts in the several figures.

This invention relates to machines for use in the manufacture of shoes and will be explained in connection with the manufacture of turn shoes, and more particularly in connection with the manufacture of turn shoes of the type largely manufactured and known as tacked heel seat shoes. In this class of turn shoes, the shoe is sewed from the heel seat on one side around the toe to the heel seat on the other side; then is "turned" and thereafter the upper at the heel seat is lasted and tacked down upon a short inside piece that is on the inside of the heel end of the finished shoe. The heel end of the sole is unsecured during this lasting operation and the operator turns it forwardly over the shank of the shoe to get it out of the way during the lasting of the heel seat. Following the lasting of the heel seat the heel end of the sole is turned down and nails are driven through the sole and the surface presented by the inserted short inside piece and the lasted over margin of the upper which has been tacked to the short inside piece, these nails being generally located within the line of tacks.

These operations are now carried on chiefly by hand. Where any machinery is employed, separate machines are employed for heel seat lasting and for sole nailing, respectively, and the shoe is handled twice, being returned to the rack between the two operations. An object of the present invention is to provide a single machine organized effectively to perform both lasting and sole securing operations on a shoe. It will be understood, however, that in many of its features the invention is not limited to an organization including both lasting and sole securing means nor restricted in utility to turn shoe work.

Important features of the present invention are to be recognized in a novel machine organization including both lasting and sole

securing means, the construction shown comprising a heel seat lasting mechanism, a mechanism for nailing the heel end of the sole down over the lasted heel seat, a shoe support, and provision for relative movements of said support and mechanisms first to present a supported shoe and said lasting mechanism in operative relation and then to present the supported shoe and the nailing mechanism in operative relation. The support in the illustrative construction is arranged to be moved to present the shoe in determinate relation to each of these mechanisms and the construction is such that shoes of all sizes may be effectively treated.

In the construction shown, the invention is embodied in a power operated machine organization in which a shoe support or carriage is arranged for power operation to slide in a guideway connecting the nailing and lasting mechanisms to present the shoe heel-end first in the lasting mechanism and then to move the shoe toe-end first under and into operative relation to the nailing mechanism, said mechanisms being operated as an incident to the presentation of the shoe in co-operative relation to them.

In the machine illustrated the lasting mechanism is open toward the nailing mechanism which presents an open space under and beyond the nailing instrumentalities into which the shoe can be moved toe-end foremost to position the heel seat in co-operative relation to the nailing mechanism. The supporting or carrying means for the shoe is arranged to have a predetermined length of movement from its position for co-operation with the heel seat tacking mechanism, which secures the margin of the upper in lasted position, into its position for co-operation with the sole nailing mechanism so that the inserted nails and tacks will be located in prearranged relation to each other. This supporting means is constructed to permit right and left shoes to be positioned with their heel ends in the same relation to the lasting mechanism and with their foreparts in reverse lateral relation to a toe rest, and is guided for movement from the heel seat lasting mechanism to the heel seat nailing mechanism to present the shoe to the nailing mechanism in the same angular relation as in the lasting mechanism. Means are provided to turn up the heel end of the sole as the shoe is

moved by its support into lasting position and to turn down said sole end upon the lasted heel seat preparatory to nailing the sole.

6 Another feature of the invention consists in a novel shoe end clamping mechanism, the construction shown comprising a heel end embracing band having operating mechanism actuated to close the band upon the 10 heel end of the shoe by movement of the shoe and the band toward lasting position. In the illustrative machine the band is arranged below and is normally projected forwardly from the position occupied by a 15 shoe in co-operating with heel seat lasting and tacking mechanism and is moved backwardly with the shoe into operative relation to the heel seat lasting and tacking mechanism and is closed as an incident to 20 its backward movement. The band is automatically locked in end embracing position.

A further feature of the invention consists in a novel and advantageous form of 25 end lasting mechanism, the construction shown comprising mechanism automatically operated to last the end of a supported shoe responsively to power operated relative movement of the shoe and said mechanism 30 into co-operative relation.

In the illustrative machine, the shoe is arranged to be moved backwardly with its support from a normal position below and forwardly of said lasting mechanism into 35 co-operative relation to the lasting devices, this movement serving to operate the seat lasting wiper mechanism to close over the bottom of the last. Preferably, and as shown, this backward movement of the shoe 40 and its support serves to close and lock the heel band about the end of the shoe in addition to causing the lasting mechanism to wipe the upstanding edge of the upper over the heel seat.

45 The end clamping mechanism is mounted on the shoe supporting carriage and is closed by the bodily movement of the carriage and shoe relatively to the heel seat lasting mechanism which is operated responsively to 50 said bodily movement and in time relation to the closing of the band. The illustrated lasting mechanism combines seat lasting wipers and gang tacking mechanism in a novel and advantageous form which constitutes a further feature of the invention. 55

Another feature of this invention consists in novel means for positioning and holding a shoe on a support or carriage movable between different mechanisms for operating 60 upon the shoe, the carriage in the construction shown being arranged for movement toward and from each of two mechanisms to move the positioned shoe successively into co-operative relation to said mechanisms, 65 means being provided for automatically re-

leasing the shoe as it moves from co-operative relation to the last of said mechanisms. As shown, the shoe is jacked back and up on its carriage into a heel end clamping band mounted on the carriage and is automatically locked in such position, the band being closed and automatically locked as the carriage moves to present the heel end of the shoe to the heel seat lasting mechanism. From this mechanism, which includes a 75 tacking mechanism, the carriage is moved along a guideway to the opposed nailing mechanism with the shoe end clamped and the heel seat lasted and with the shoe locked on the carriage in the position in which it 80 was lasted, to present the heel end of the shoe to the nailing mechanism in the same angular relation to said mechanism that it formerly occupied relatively to the lasting mechanism. From this position, the carriage is moved to a point between the two 85 mechanisms, the locking devices being operated through certain abutments to release the shoe which is unjacked and ready for removal. The locking of the shoe on its 90 carriage enables it to be presented in the same positional relation to opposed tacking and nailing mechanisms and ensures determinate relation between the inserted 95 tacks and nails. The construction provided insures that the points of insertion shall 100 not be aligned or overlapped and that the nails be determinately positioned properly to secure the heel end of the sole to the heel seat.

A further feature of the invention consists in novel pressure means movable to lay and hold the heel end of the sole down on the heel seat with heavy conforming pressure preparatory to the driving of the nails 105 into the sole. In the illustrative machine, a combined sole pressing and nailing head is forced down upon the sole under heavy spring pressure prior to and during the 110 driving of the nails.

Another feature of the invention consists in novel controlling means, the construction shown comprising starting means for a power operated nailing mechanism for operating upon a shoe which is operated responsively 115 to movement of a shoe supporting means to position a supported shoe in co-operative relation to said mechanism. The actuation of the starting means will thus take place in time relation to the movement of the shoe and will expedite the operation as well as relieve the operator. As shown, the shoe supporting carriage is moved along a guide way to present the shoe in proper relation to the nailing mechanism, and a starting clutch is operated by the moving carriage at the proper time.

A further feature of the present invention consists in novel means for feeding fasteners to an inserting mechanism responsively 120 125 130

to movement of a shoe relatively to said mechanism. In the construction shown a lasting tack inserting mechanism forming part of a heel seat lasting mechanism is opposed to and connected with a sole nail inserting mechanism by a guideway along which a shoe supporting carriage is moved successively to present the supported shoe to the action of the tack inserting and nail inserting mechanisms respectively, which mechanisms include tack and nail supplying means. As the shoe carriage is moved to position the shoe to co-operate with the heel seat lasting and tacking mechanism, tack and nail separating and distributing means are actuated responsive to said movement of the carriage to cause sets of tacks and nails to be fed to both the tack and nail inserting mechanisms. These fasteners are, therefore, positioned for driving into the wiped over upper and the sole respectively, when the shoe reaches positions of co-operation with the respective tacking and nailing mechanisms.

The above and other novel features of the invention not specifically recited are described in detail in the following specification and pointed out in the appended claims.

In the accompanying drawings illustrating a preferable embodiment of the invention and forming part of this specification—

Fig. 1 is a front elevation of a machine constructed in accordance with the present invention, the shoe carriage and operating mechanisms being positioned as at the beginning of the machine cycle,

Fig. 2 is a view in elevation of the left hand end of the machine shown in Fig. 1,

Fig. 3 is a view in elevation of the right hand end of the machine of Fig. 1, parts being shown in section,

Fig. 4 is a perspective detail view illustrating the heel clamping and heel seat lasting and tacking features of the invention,

Fig. 5 is a perspective view of the shoe carriage with a shoe mounted thereon and clamped by the heel band and showing the connected operating parts for the tack separator and distributor.

Figs. 6, 7 and 8 are, respectively, views in side elevation, to plan and end elevation of the shoe supporting carriage,

Fig. 9 is a detail view illustrating the sole pressing and nailing mechanism,

Fig. 10 is a perspective view of the heel seat wiper-tackers and certain operating and adjusting parts.

Fig. 11 is a top plan of the wiper-tackers closed over the heel seat of a shoe, and

Fig. 12 is a detail of the clutch operating means for the sole nailing mechanism.

The frame of the machine, as shown, comprises a series of superposed sections 2, 4 and 6 providing spaced walls or housings between or within which portions of the ma-

chine mechanism are disposed and supported. A power driven shaft 8 has one end journaled in and extending through the back wall of the base section 2 and has its other end journaled in the upper end of a standard 10 (Fig. 2) uprising from the floor or other support rearwardly of said wall. A pulley 12 with its hub 14 is freely revoluble on shaft 8 and is continuously driven through a belt from a suitable source of power such as a line shaft or motor. A suitable clutch disk 16 of known type is fixed to shaft 8 and is normally held disconnected from pulley 12 by a dog 20 which engages with one of a plurality of stop shoulders or notches 18 on the periphery of the sleeve of said clutch disk. The dog 20 is pinned to a rock shaft 22 having its rear end journaled in the standard 10 and its front end journaled in and extending through the rear wall of the base 2. A tripping lever 24 (Figs. 1 and 2) pinned to the front end of said shaft has a depending plate normally positioned by a spring attached to said lever to be engaged by the clutch tripping plate 26 on the upper end of a spring retracted arm 28 operated by a treadle 30 at the front of the frame. To start the rotation of the shaft 8, the operator depresses the treadle and immediately releases it, momentarily throwing the dog 20 out of engagement with a shoulder 18 and permitting the clutch to operate to turn the shaft until the next shoulder 18 is engaged by the dog which is immediately returned to engage the periphery of the clutch disk when the treadle is released.

Between the pulley 12 and the rear wall of frame section 2, two sprocket wheels 32, 34 are mounted on and continuously rotate with the hub 14. These sprocket wheels through suitable connecting chains drive co-operating sprocket wheels 36, 38, on shafts 40, 42, journaled respectively in the walls of sections 6 and 4 of the frame and operating the tack lifters of tack hoppers of known construction forming parts of certain tacking and nailing mechanisms later to be described.

The outer or front end of shaft 8 carries a crank arm 44 positioned between the walls of frame section 2 and connected by a link 46 to a lever 48 which is pivoted to the frame at 50 and has its upper end connected by link 52 to a bracket 54 rigidly secured to the base 56 of a reciprocable support or carriage for the shoe supporting and clamping means. The base 56 is supported by and guided in ways 58 formed on the inner faces of the walls of frame section 4 (see Fig. 4) for reciprocation lengthwise of the machine frame through movement of lever 48 effected through crank arm 44 of the driven shaft 8.

The upper face of the base 56 is longi-

tudinally and centrally channeled to receive and guide the base plate 60 of a shoe supporting jack. The left end of this base plate, as viewed in Fig. 1, has its upper face 5 channeled to receive an adjustable toe supporting plate 62. A pin 70 (Fig. 6) extends downwardly through the toe plate and is insertible in a longitudinally extending series of holes in the base plate 60 to adjust 10 the position of the toe support relatively to the shoe. The toe plate 62 has an interiorly threaded boss 64 receiving the threaded stem 66 of a toe rest 68 arc-shaped in a horizontal plane. The edge flanges of 15 the base plate 60 and of the toe support 62 are enclosed between the base 56 and the overlapping edges of retaining strips 72 secured to the side edges of said base.

The rear end of base plate 60 is formed 20 with an enlargement 74 having a vertical passage through which a heel post 76 carrying a heel pin 78 at its upper end is guided for vertical movement. A last and shoe mounted on the heel post may be swung laterally 25 so that right and left shoes may be positioned with their heel parts in the same relation to a heel lasting mechanism and with their fore parts in reverse lateral relations to the toe rest. The enlargement 74 projects upwardly from plate 60 and also has 30 a portion extending downwardly through an elongated opening in the base 56. The plate 60 is connected to the base 56 of the shoe carriage by a toggle 80 connecting the 35 lower end of enlargement 74 with bracket 54 at the opposite end of base 56, the toggle being normally broken by a spring connecting the links of the toggle. It may be straightened to move the plate 60, which 40 forms a shoe jacking slide, to the right as viewed in Fig. 1, by means of a plate 82 carried at the upper end of a rod 84 which is moved upwardly to straighten the toggle by a treadle 86.

45 A stud 73 in the base of heel post 76 rides over a spring-pressed lever 75 carried by base 56 when the toggle is straightened and lifts up and yieldingly presses the bottom of the last and sole against the end of a 50 height gage 81 adjustable longitudinally in an arm 83 swiveled in a bracket 85 attached to an upper frame section 6 and having a depending hold back plate 87 rearwardly of the height gage and permanently positioned. The heel post is locked in its raised position with the bottom of the last and sole against the gage by an eccentric 79 bearing against the post and having a stem journaled in enlargement 74 and projecting outwardly from the enlargement. An arm 831 attached to the projecting end of the stem is normally pulled by an attached spring in a direction to cause the eccentric to oppose downward movement of the heel post. An

anchor pin 851 for this spring projects outwardly from the arm. 65

This movement of jacking slide 60 toward the right in the illustrated machine operates to position the extremity of the heel end of the shoe against a clamping 70 band. The base 56 of the reciprocable carriage is formed with an upstanding head 57 (Figs. 5-8) having its upper face longitudinally grooved to support and guide for longitudinal movement a spring pressed 75 plunger 88 which operates to close a heel clamping band 90 having links 92 connecting its forward ends with the adjacent ends of band closing levers 94 having their rear ends overlapped and formed with cam slots 80 96 therein. A stud or roller 98 upstanding from the plunger 88 enters both cam slots and, in the normal rearward spring-pressed position of the plunger, serves to position the levers 94 to hold the ends of the band 85 90 opened out. These levers are overlapped and pivotally mounted on the top face of the head 57 by means of pivot studs 100. The upper face of head 57 at its forward end has an upstanding lug 102 provided 90 with a forwardly projecting end 104 forming a back stop for the clamping band 90 and also providing an abutment arranged to engage certain novel heel wiper mechanism when the clamping band 90, base 56 95 and head 57 are subsequently moved bodily backward through lever 48 as later described.

The frame section 4 of the machine as viewed in Fig. 1, is formed with upward extensions 4^a and 4^c at the left and right hand ends of the machine, respectively, and with an upward extension 4^b intermediate of the ends of the machine and enclosing the head 57 of the sliding shoe support or carriage in the position of the carriage at the beginning of a cycle. The upward extension 4^c in line with the plunger 88 (see Fig. 1) has a socket 100 which receives a yielding adjustable abutment plug 106 normally pressed toward the end of the plunger 88 by a coiled spring sleeved on the threaded adjustment rod 108 which extends from the plug and through the end plate of extension 4^c and is adjusted by suitable means such as the nut shown in Fig. 1. After the treadle 86 has been operated to jack the shoe backwardly against the heel band and to lift it upwardly against the height gage which acts temporarily to turn back the heel end of the sole, the gage pin 81 on the arm 83 is swung upwardly out of the way (see Fig. 5), the treadle 30 is operated to clutch shaft 8 to the driving pulley 12 and through crank arm 44, link 46 and lever 48 to cause the shoe carriage base 56 with its head 57 and the last and shoe to be moved bodily backward or to the right as seen in Fig. 1. The end of plunger 110

115

120

125

88 will contact with abutment plug 106 in the course of this movement and, as the base 56 and head 57 continue to move rearwardly, the stud 98 will act against cam slots 96 to close the band 90 tightly against the heel end of the shoe. The abutment 106 will yield to permit the full stroke of the shoe carriage 56 to the right after the band has been tightly closed about the shoe. The 10 plunger and band are locked in this shoe clamping position by an eccentric roll 110 journaled in the head 57 and having a projecting crank arm 112 at the outer face of said head. A releasing lever 113 is pivoted 15 to the side of head 57 below crank 112 and co-operates with a pin 115 on the inner face of the frame in a manner hereinafter explained. The backward movement of the carriage 56 is halted when the dog 20 engages the next adjacent notch 18 (Fig. 1) on the clutch disk sleeve, the carriage 56 now being at the extremity of its movement toward the right hand end of the machine. When the shoe supporting jack is moved 25 backwardly into the heel band, it is locked in position on the carriage 56 by means of an eccentric roll 114 (Fig. 4) journaled in the enlargement 74 of the shoe jacking plate 60 and engaging a retaining strip 72 on the 30 base 56 of the shoe carriage. The eccentric roll has a crank arm 116 alined horizontally with arm 831 of the heel post eccentric and normally pulled downwardly by a spring (Fig. 4) to cause the eccentric to lock 35 against the strip 72 to hold the slide 60 in jacked-back position on the base 56 of the sliding shoe carriage. The anchor pin 118 for this spring projects outwardly from the arm 116 and with anchor pin 851 of the heel post eccentric arm is arranged for engagement with a releasing member at the opposite end of the machine as later described.

The upper ends of the upward extensions 4^a, 4^b, 4^c of the frame are flanged to receive 45 flanges at the bases of the spaced plates forming the walls of the upper sections 6 of the machine frame. The base of the upper section 6 at the extreme right end of the machine as viewed in Fig. 1 overlaps and is 50 connected to the base of the next adjacent or intermediate section 6, as seen in Fig. 1. This extreme end section supports a tack feeding hopper 120 of known construction whose tack lifter is continuously rotated 55 through a pulley 122 (Fig. 1) on the hub of the sprocket wheel 38 on shaft 42 and a suitable connecting belt crossed and passing over connected tension pulleys 124, 126 (Figs. 1 and 3). From the hopper 120, a 60 plurality of raceways of known construction indicated generally at 128 extend down to a tack separator and distributor 130 also of known construction and which may or may not correspond to that disclosed in

United States Patent No. 1,002,421, of Sept. 65 5, 1911.

To reciprocate the slide of this distributor, an inclined cam way 132 is attached to the back face of head 57 of the sliding shoe carriage. A rock shaft 134 is journaled on 70 the frame sections 4^a, 4^b (Fig. 1), and adjacent to its right hand end, as viewed in Fig. 1, is provided with a rock arm 136 (Fig. 5) having a roller on its end entering in the inclined cam way 132 and moved to 75 the lower end of said cam way to rock arm 136 downwardly when the sliding shoe carriage 56 is moved to the right hand end of the machine (see Fig. 5) to close the heel band, and, as will be seen later, to wipe the 80 edge of the upper over the heel seat and to tack it down. Preferably, means such as a spring 137 and stop pin 139 (Fig. 5) will be employed to position the end of rock arm 136 for entry into the cam way. The extremity of the rock shaft adjacent to this cam way and rock arm 136 carries a crank arm 138 (swung upwardly by downward rocking of arm 136) to the end of which is attached a block 140 sliding on the lower 90 end of a rod 142 against the tension of a coiled spring 146 sleeved on the lower end of the rod and bearing against a collar 144 pinned to the rod.

This spring is a "safety" spring and 95 yields when the tack separating and distributing slide in moving becomes caught on a tack. The upper end of this rod and the end of the lower arm of a bell crank lever 148 have a ball and socket connection, the 100 lever 148 which is journaled in a bracket on the frame section, having its other and upper end connected by a rod 150 to the operating slide of the tack separator and distributor 130.

Upward movement of crank arm 138 when the carriage 56 is moved to the right to close the heel band moves the distributing slide in the direction to feed a set of tacks, in the present showing eight, from the separator and distributor downwardly through a series of tubes 152 into tack channels 154 (Fig. 4) extending downwardly from the upper edge of a combined wiping and tacking member best seen in Figs. 4, 10 and 11. This 115 member comprises complemental vertically extending plates 156 curved to conform substantially to the curvature of the heel end of a last and pivotally interconnected at their rear ends, a laterally extending flange 158 being formed at the base of the plates to support them between the flanged upper edges of the section plates 4 and the flanged lower edges of section plates 6 of the frame as best seen in Fig. 4. The plates are reduced in thickness between their upper and lower edges to form shoulders (Figs. 4, 10 and 11) and are formed with lateral slots 120 125

at their rear ends in line with their connecting pivot pin. Complemental operating levers 160 rest upon and are secured to these shoulders and have their ends overlapped 5 and formed with eyes extending in these lateral slots of the plates 156. The pivot pin of the plates 156 extends through these eyes and connects the operating levers so that functionally they form a part of and extensions 10 from the plates. Apertures are formed in these plates in line with the upper ends of the inclined tack channels 154 in the plates 156 to receive the ends of the tack feeding tubes 152. The levers 160 are provided 15 with lateral extensions 162 having laterally elongated slots therein adjacent to their outer ends through which studs 164 extend into the bottom flange of the frame sections 6 as shown in Fig. 4.

20 The tack channels 154 terminate adjacent to the base of the plates 156 in tack pockets. The plates 156 in line with these tack pockets are formed with vertical bores 166 in which are seated tack drivers 168, the upper 25 ends of which project above the top of the plates 156 and are flanged. Springs sleeved on the drivers between their end flanges and the top of plates 56 tend to hold the lower ends of the drivers above the tack 30 pockets to permit tacks to be fed down the inclined channels 154 and into these pockets. Tack holding blocks 169 of known construction which may or may not correspond substantially to those disclosed in United States 35 Letters Patent No. 999,327, of August 1, 1911 are dovetailed in the base of the plates 156 (Figs. 4 and 10) and are constructed to permit the tacks to be driven from the blocks and into the overwiped edge of the upper 40 when the drivers 168 are forced downwardly.

The lower inner edges and bottom faces of the plates 156 form heel wipers positioned in a plane slightly above the plane of the top edge of the heel band 90, the plates and wipers being normally spread or opened out by an interposed coiled spring 170 (Figs. 4 and 11) anchored to the flanged ends of opposed screw-studs 172 which extend 45 through threaded bores in the plates 156 adjacent to their upper edges. These screw studs may be operated to vary the tension of spring 170 and to adjust the contour defined by the edges of the wipers substantially to the contour of the heel seat to be lasted so that wipers may be quickly adjusted for right and left lasts and will be effective snugly to draw the upper to the in-curved side of the heel and the rear of the 50 shank at the inner side of a last.

A bar 174 connected to the plates 156 by their pivot stud (see Figs. 10 and 11) extends rearwardly from the rear ends of these plates and is connected to a link 176 having 55 an elongated slot in its end through which

extends a pin carried by a lever 178 pivoted at one end to the base of frame plate 6 (Fig. 1). This lever carries a tooth co-operating with a ratchet on the bottom edge of frame plate 6 (Fig. 1) by means of which the position of its pin relatively to the slot in link 176 may be adjusted to vary the extent or limit of closing movement imparted to the wipers by backward movement of the last and shoe on carriage 56. The lever may be sprung downwardly to release its tooth from the ratchet in making this adjustment which is desirable to adapt the wipers for operating upon wide and narrow heels.

The bar 174 is formed with a toothed plate 180 on its under side to which the upper toothed face of an abutment plate 182 is adjustably connected by suitable means such as the slot and clamping bolt shown in Fig. 10. The plate 182 has a downward extension 184 at its forward end which is positioned in the plane of rearward movement of the lug 102 on the head 57 of carriage 56. When treadle 30 is operated to cause the carriage to be moved rearwardly to close the heel band upon the end of the shoe and last, as described, the edge of the upper at the rear extremity of the shoe is engaged by the edge of the wipers at their rear ends, and wiped over and down upon the last bottom by the time the lug 102 and abutment 182 contact, the position of the abutment determining the extent of movement of the wipers over the central rear end of the last and predetermining the tacking point. Rearward movement of the carriage 56 continues after the lug and abutment contact, the abutment being now moved rearwardly and moving the abutting ends of the wipers rearwardly, causing the wipers to fulcrum on the studs 164 (see Fig. 11) and swing inwardly over the edge of the last bottom with a rearward component of movement until the stud on lever 178 contacts with the end of the slot in link 176 and prevents further closing movement. The studs 164 upon which the wiper plates fulcrum are located substantially in line with the rear ends of the wipers and therefore cause the wipers to swing in over the sides of the last with a lengthwise heelward component of movement. The adjusted position of the stud on lever 178 relatively to the end of the slot in link 176 determines the extent of closing movement of the wipers and also the tacking points at the sides of the heel end of the shoe since the wipers and tacking blocks are integrally connected and in permanent relation. The band is firmly closed upon the sides of the upper at the heel end of the last when the wipers swing in over the sides of the heel seat so that the indrawing pressure of the wipers against the edge of the upper cannot displace the upper on the last, the abutment 106 yielding to permit continued movement of 130

the shoe carriage after the heel band has been closed. Preferably, the ratchet on the base of frame 6 which co-operates with the tooth of lever 178 will bear a scale or numerals indicating the extent or proportionate extent of closing movement provided by the various adjustment notches, and the bar 180 will have similar indications for the distance of the tacking point from the edge of the last end provided by the various adjustment notches. To allow for lost motion between the lever 48 and carriage 56 when the lever 178 arrests rearward movement of the carriage and closing movement of the wipers, the link 52 may be constructed as shown in Figs. 6 and 7, a stiff coiled spring 541 being interposed between telescoping portions of the link.

When the carriage 56 has reached the end of its movement toward the right and the dog 20 has engaged the next adjacent notch 18 on the clutch disk sleeve to disconnect shaft 8 from the driving pulley and to bring carriage 56 to rest, the heel end of the upper will have been clamped to the sides of the last by the band; its upstanding edges will have been wiped over the heel seat (hold back plate 87, Fig. 4, having held the end of the sole turned back); and a set of tacks 30 will have been fed down the tack channels 154 to rest against the lower ends of the driver rods 168, which at this point in the operation, are lowered to project their ends in the line of the tack channels through depression of their heads by a driving plate 186. This plate is supported at the lower end of a vertically guided rod 188 whose upper end is connected by a link 190 to one end of a lever 192 having a pivot pin at a point between its ends which is journaled in a bracket 194 (Figs. 1 and 3) upstanding from the machine frame.

A strong coiled spring 196 tends to swing the long arm of lever 192 downwardly to operate the tack driving plate 186. The lever is moved against the tension of this spring by a latch 198 pivoted to the upper end of a vertically extending controlling rod 200 and pulled inwardly to engage the end 50 of the short arm of lever 192 by a coiled spring extending from the latch to a link 201 pivoted on the bracket 194 and on the pivot pin of the latch and serving to guide the rod 200 in its vertical movements. A nose 199 on the latch is arranged to engage a wedge face 203 (Fig. 3) on bracket 194 when the rod and latch are lowered to move the latch outwardly against the tension of its spring and to release the end of the lever 192 so 60 that the tacks may be driven. The latch is in its lowered position when the carriage 56 is moved to the right as previously described, and the driver rods 168 are depressed by the spring 196.

65 The lower end of rod 200 carries a lat-

erally offset roller riding in a cam groove in the face of a cam 202 (Figs. 1 and 3) loose upon shaft 42 between the sprocket wheel 38 and a clutch disk 204, both of which are pinned to the shaft and are continuously rotating. A bracket 206 is laterally outstanding from the cam 202 and on this bracket an eccentric roll 208 is journaled, its spindle 210 extending outwardly and downwardly from the bracket and normally tending to swing the roll to clutch the disk 204 to cam 202. A fin 212 upstands from a sleeve 214 loose on shaft 42 and slidable longitudinally against the tension of a coiled spring 216. This fin engages the downwardly bent end of spindle 210 and normally prevents the eccentric roll from turning in the direction to clutch rotating disk 204 to the cam 202. The sleeve and fin may be displaced to permit this clutching action to take place by suitable means such as a knee or thigh operated plate 222 at the outer end of a rod 220 which may be moved to engage an arm 218 depending from sleeve 214. This may be effected as the carriage 56 moves to clamp the end of the shoe and to wipe the edge of the upper over the heel seat. It is within the scope of the invention, however, to operate this clutch automatically responsively to movement of the carriage to present the shoe in tack-receiving position. The plate 222 is intended to be released immediately after it has been pushed inwardly, the fin 212 returning to its original position and engaging spindle 210 at the end of one revolution of cam 202 to disconnect said cam and its clutch disk 204. At the beginning of the cycle of rotation of cam 202 the cam groove in the side face of this cam (see Fig. 1) operates to lift rod 200 causing latch 190 to engage over the end of the short arm of lever 192. Thereafter the rod 200 is lowered, pulling up the long arm of the lever 192, tensioning the spring 196 and permitting the springs of the driver rods to lift the driver rods, allowing the tacks fed into the tack channels 154 by the heel clamping and wiping movement of carriage 56 to drop into the tack pockets. As the rod 200 continues to lower, the nose 199 of the latch 70 engages the wedge 203 (see Fig. 3) and the latch is swung outwardly, releasing lever 192 and permitting its spring 196 to snap it downwardly. The driver plate 186 is thereby snapped down against the heads of the driver rods 168 causing them to drive the tacks into the overwiped upper. The rod and latch remain in this lowered position during the remainder of the cycle of cam 202 and are raised at the beginning of the next cycle as previously described.

The shoe is now conditioned for the laying and nailing of the heel end of the sole. Certain instrumentalities are provided at the opposite or left hand end of the machine as

viewed in Fig. 1, for effecting this result. The frame section 6 at the left end of the machine as viewed in Fig. 1, has a nail hopper 224 mounted in a supporting bracket 226 and having a series of raceways indicated generally at 228, leading to a nail separator and distributor 230, all of known type and which may correspond to the described tack hopper, tack feeding, separating and distributing means at the opposite end of the machine. The tack lifter for hopper 224 is continuously rotated by a belt connection to a pulley 244 connected to the sprocket 36 which is loose on shaft 40 and is continuously rotated through sprocket 32 on the hub of driving pulley 12. The slide 232 (Fig. 2) of the nail separator and distributor is operated through the rock shaft 134 when the latter is oscillated in the clamping and wiping of the upper, a bell crank lever 234 (Fig. 2) being connected to said slide and operated by a rod 236 pivoted at its lower end to a crank arm 238 fixed to said rock shaft. The construction and operation are similar to that of the slide operating parts of the tack hopper at the right end of the machine, a safety spring 240 being similarly interposed between a block attached to the end of the crank arm and a second block 242 on the rod above its lower end.

From the nail separator 230 the nails are fed by tubes 246 to openings 249 in the flanged base 248 of a stationary member having a sleeve 250 in which a vertically moving nail driving plunger 252 is guided, said plunger having a nail driving plate 254 at its lower end from which a series of fixedly attached depending nail drivers 256 extend down through vertical bores 258 in a sole pressing and nailing head 260. This head is also bored to provide a series of nail feeding passages 262 alined with the openings 249 and inclined to form junctions with the driver bores 258 adjacent to the lower end of the head, nail holding pockets being formed at this point and nail blocks 264 of known type which may correspond to the tack blocks previously described, being mounted in the bottom face of the head 260 below said nail pockets. The head is guided for vertical movement, and nail feeding openings 249 and nail passages 262 are maintained in operative alinement by means of ribs 266 guiding between parallel walls 268 at the inner sides of frame plates 6 as best seen in Figs. 2 and 9.

The sole pressing and nailing head 260 is raised and lowered relatively to the nail driving plate and the supported shoe and last through connections operated from shaft 40. A curved lever 272 journaled on a spindle 274 supported between the plates of frame section 6 has a pin and slot connection at one end with a lug 270 laterally offset from said head and has its other end bifur-

cated at 276 (Fig. 2) to embrace and journal on pins 278 outstanding from a sleeve 280 against the lower end of which the upper end of a coiled spring 282 abuts. This spring is sleeved on the lower end of a rod 284 between said sleeve 280 and a tensioning nut on the rod. The rod extends upwardly through and above said sleeve and is pivoted to one end of a laterally curved lever 286 (Figs. 2 and 9) the other end of which is journaled on spindle 274 (Fig. 9). Between its ends a roll 288 bears upon the periphery of a cam 290 fixed to cam shaft 40 and best seen in Figs. 2 and 9. Upward movement of lever 286 through the action of peripheral cam 290 against said roll will compress spring 282, turning lever 272 on its pivot 274 and yieldingly forcing the sole pressing and nailing head 260 downwardly causing the base of said head to engage and press down hard on the heel seat of a shoe the heel end of the sole into which nails are subsequently driven. During this movement, the nail driving rods 256 are stationary so that the nails fed into the channels 262 and previously stopped by the driver rods may now drop down into the nail pockets of the nail blocks.

The nail driving plunger 252 has its upper end connected by a link 292 with the long arm of an operating lever 294 journaled between its ends in a bracket 296, uprising from the frame section 6. A strong coiled spring 298 normally tends to throw downwardly the long arm of said lever. The end of the short arm of the lever is held by a latch 300 pivotally mounted upon the upper end of an operating rod 302 guided in its vertical movement by a link 304 pivotally mounted on the latch pivot and on the bracket 296. A coiled spring connects the latch and said link and normally tends to pull the upper end of the latch inwardly to engage over the end of lever 294. The latch is formed with a nose 295 designed to be engaged by a cam surface 297 on the bracket edge to swing the latch outwardly to release lever 294 to drive the nails into the sole. The lower end of rod 302 is pivoted to one end of a lever 306 journaled on the machine frame and having a roll 308 at its other end engaging the periphery of a cam disk 310 pinned to shaft 40 and normally inactive. The roll 308 is held pressed against the peripheral cam surface by suitable means such as a spring (Fig. 1). In the inoperative position of the parts with cam 310 at rest the rod 302 is in partially lowered position (Fig. 2), with the latch nose 295 positioned to be engaged and moved outwardly to release lever 294 upon further lowering of the rod. The cam 310 is figured to lift the roll 308 and further to lower the rod 302 toward the end of a cycle of the cam after the head 260 has pressed the heel

end of the sole down on the heel seat of the shoe. Subsequently the rod is lifted to cause the latch 300 to engage and latch over the end of the lever and then the rod is lowered 5 to the position it occupies at the beginning of a cycle as described and as best seen in Fig. 2.

The sole pressing and nailing head is lowered and the nails are driven through 10 rotation of the cam shaft 40 by means controlled and operated by the carriage 56 as it moves from the right end to the left end of the machine. Adjacent to cam 310 a clutch disk 312 is mounted on the hub 15 of sprocket wheel 36 to rotate continuously therewith. The cam 310 is provided with a bracket 314 in which is journaled the spindle 318 of an eccentric 316, the spindle extending out beyond the opposite face of the 20 cam and being bent downwardly. This spindle normally tends to swing the eccentric 316 in the direction to bind on clutch disk 312 and to clutch said disk to cam 310. This action is normally prevented by an inclined 25 plate 322 attached to the beveled end of an arm 320 (Figs. 1 and 2) which plate engages the bent end of spindle 318 and prevents the eccentric from turning to connect the cam 310 and rotating disk 312. The arm 30 320 extends lengthwise of the machine from the cam disk (see Fig. 1) and is provided with a hub 324 splined on the end of spindle 274 which projects beyond the rear wall of the frame and which has a coiled spring 35 326 sleeved thereon and tensioned against the arm 320 to hold the arm in position to render the nail driving mechanism inoperative. The hub portion of the arm on the opposite side from the spring 326 is formed 40 as a wedge and a vertically sliding plate 330 is formed with a co-operating wedge face 332 (Fig. 2) and is slotted to guide on spindle 274 for vertical movement to force the arm 320 backwardly and thus to release the spindle 318. A link 334 depends from the lower 45 edge of plate 330 and is connected to a crank arm 336 carried at the rear end of a rock shaft 338 journaled in a bearing in the rear plate of the frame and having its forward end positioned between the plates of the 50 frame. To this forward end is attached a second crank arm 340 extending at an angle to the first crank arm and carrying at its lower end a pivoted contact link 342 having 55 an extension to engage and turn crank arm 340 when the contact link is engaged and turned by a lug 346 (Figs. 1, 2, and 6) standing from a strip 72 on the base 56 of the shoe carriage when said carriage is 60 moved from the right end of the machine to the left end. A coiled spring such as shown, or other suitable means, normally tends to swing crank arm 340 to move plate 330 upwardly to inactive position as shown in Figs. 2 and 12. When the carriage is re-

turned to its original position at the right hand end of the machine, contact link 342 is turned without actuating crank arm 340.

A link 348 is pivoted to the frame at the inside face of a frame plate with its lower 70 end resting in a slotted abutment lug 350 (Figs. 1 and 2) the edge of the link being in line with the pins 118 and 851 of the arms of eccentrics 114 and 79 which lock the heel spindle and last carrying slide in position 75 on carriage 56.

It will be seen that with the described and illustrated arrangement of the heel seat lasting and tacking mechanism and the sole nailing mechanism, the seat lasting and 80 tacking mechanism is open toward the nailing mechanism, to receive a shoe heel end foremost and the nailing mechanism presents an open space under and beyond the 85 nailing instrumentalities into which the shoe may be moved toe end foremost to bring the heel seat under the nailing instrumentalities.

With the construction and arrangement 90 of these various mechanisms in mind, it will be seen that the operation of the machine is as follows: The workman, after adjusting the toe post 66 for length of shoe, turning down the height gage 81, and if necessary, adjusting the wiper-tackers through screws 95 172 and making any of the described adjustments of lever 178 and abutment 182 for the extent of overwipe and the tacking line, then depresses treadle 86 to slide the shoe relatively to its carriage and back against 100 the heel band, the lever 75 elevating the heel pin to press the heel seat against the gage pin 81. The parts are locked in this position by the eccentrics 79 and 114 as described. The height gage pin 81 is now 105 turned up (as shown in Fig. 5) and the workman depresses momentarily the treadle 30, throwing in the driving clutch, whereupon the power means through lever 48 moves the carriage 56 with the jacking 110 slide and its supported shoe and last bodily to the right as viewed in Fig. 1, clamping the heel band about the heel end of the shoe and wiping the edge of the upper over the heel seat as described. The hold back plate 115 87 acts in this movement of the shoe to engage and turn back the heel end of the sole out of the way of the wiper-tackers. This movement of the carriage turns the rock 120 shaft 134 and through the described connections operates the separating and distributing devices of the tacking and nailing mechanisms at the opposite ends of the machine, thereby feeding sets of tacks and nails for the subsequent heel seat tacking and sole 125 nailing operations. The workman now presses inwardly the plate 222 operating the clutch which actuates the tack driving mechanisms. When the tacks have been driven, the treadle 30 is again depressed and lever 130

48 moves the carriage 56 with the clamped last and shoe to the left hand end of the machine as viewed in Fig. 1. During this movement of the carriage, the lever 113 5 slides over and is swung by pin 115 without engaging its upper end with arm 112 of the clamping plunger eccentric lock; pins 118 and 851 engage, lift up and pass beyond the link 348 since their eccentrics 79 and 10 114 lock them against depression by the link; and the lug 346 on the carriage 56, engages and passes beyond contact link 342, turning said link and the connected crank arm 340 in a direction to operate the 15 scribed wedging device to throw in the clutching eccentric 316 and cause rotation of the cam shaft 40, the plate 322 being returned by spring 326 into position to turn the eccentric to unclutch at the end of one 20 revolution of the cam shaft. The upturned heel end of the sole will also engage the nailing base of head 260 which is lowered as the heel seat moves into position therebeneath, and will be laid down on the heel seat before pressure is applied by said head. 25 At the beginning of the revolution of the cam shaft 40, the cam 290 operates to depress the sole pressing and nailing head 260 moving it downwardly relatively to the nail 30 driving head and drivers to press the heel end of the sole hard down on the heel seat as described and thereafter the cam 310 becomes operative to release the latch 300 to permit the lever 294 to be actuated to drive 35 the nails into the heel end of the sole. The driving head 254 with its drivers has a long driving stroke owing to the previously effected movement of the nailing head. The head 260 and the member 254 are then 40 turned to their starting positions. Since the carriage 56 has a definite limit of movement toward the left, the heel end of the sole will always occupy a determinate position relatively to the nailing head to locate 45 the nails in prearranged relation to the previously inserted tacks. The shoe carriage is also guided to carry the shoe to the nailing mechanism in the same angular relation to the machine which it occupied in the heel 50 seat lasting mechanism, thereby ensuring a definite relation in the relative locations of the tacks and nails.

After the nails are driven into the heel seat the operator again depresses treadle 30 55 and the carriage is moved toward the right and is automatically stopped in the position illustrated in Fig. 1. During this movement to the right, the lug 346 turns link 342 without moving crank arm 340 and the connected clutch parts; the pins 118 and 851 ride over the upper edge of the link 348 which is held against depression by abutment lug 350 and are turned by the inclined edge of said link to swing their eccentrics 60 65 in the direction to release the shoe jacking

slide and heel post and the lever 113 engages pin 115 to swing in the direction to engage and turn arm 112 to release the locking eccentric of the band closing slide so that the last and shoe are unjacked as shown in Fig. 1. The operator now removes the released shoe and last and the machine is ready for another cycle of operations.

While the described machine is particularly useful in the manufacture of turn 75 shoes of the tacked heel seat type and has been so described, it is recognized that the mechanism forming the subject-matter of this invention has a wider field of application and the invention as defined in the 80 claims is not intended to be so limited except as expressly stated or as required by the context.

Having described my invention, what I claim as new and desire to secure by Letters 85 Patent of the United States is:—

1. A machine of the class described having, in combination, heel seat lasting mechanism, mechanism for nailing the heel end of the sole over the lasted heel seat, and a shoe 90 support, said mechanisms and support being constructed and arranged for relative movements first to present a supported shoe and said lasting mechanism in co-operative relation and then to present the heel end of the 95 supported shoe and said nailing mechanism in co-operative relation.

2. A machine of the class described having, in combination, heel seat lasting mechanism, mechanism for nailing the heel end of the sole over the lasted heel seat, and a shoe 100 support constructed and arranged for movement first to present the heel end of a supported shoe in co-operative relation to the lasting mechanism and then to present the 105 heel end of said shoe in co-operative relation to said nailing mechanism.

3. A machine of the class described having, in combination, heel seat lasting mechanism, mechanism for nailing the heel end of the sole over the lasted heel seat, a shoe support constructed and arranged for movements of determinate extent first to present the heel end of a supported shoe in co-operative relation to the lasting mechanism, and then to present the heel end of said shoe in 110 co-operative relation to the nailing mechanism, and power operated means for moving said support successively to present a supported shoe to said mechanisms.

4. A machine of the class described having, in combination, heel seat lasting mechanism, mechanism for nailing the heel end of the sole over the lasted heel seat, a shoe 115 support, said mechanisms and support being constructed and arranged for successive relative movements first to present a supported shoe and said lasting mechanism in co-operative relation and then to present said shoe 120 and the nailing mechanism in co-operative 125 130

relation, and manually controlled power operated means for effecting successively said relative movements of the shoe support and the lasting and nailing mechanisms.

5. A machine of the class described having, in combination, heel seat lasting mechanism, mechanism for nailing the heel end of the sole over the lasted heel seat, a shoe support, said mechanisms and support being

10 constructed and arranged for successive relative movements first to present a supported shoe and said lasting mechanism in co-operative relation and then to present said shoe and the nailing mechanism in co-operative

15 relation, and means for operating one of said mechanisms in time relation to the relative movement of the shoe support and said mechanism into co-operative relation.

6. A machine of the class described having, in combination, heel seat lasting mechanism, mechanism for nailing the heel end of the sole over the lasted heel seat, a shoe support, said mechanisms and support being constructed and arranged for successive relative

25 movements first to present a supported shoe and said lasting mechanism in co-operative relation and then to present said shoe and the nailing mechanism in co-operative relation, and means actuated by presentation of the shoe in co-operative relation to one of said mechanisms for causing said mechanism to operate upon the presented shoe.

7. A machine of the class described having, in combination, heel seat lasting mechanism, mechanism for nailing the heel end of the sole over the lasted heel seat, a shoe support, said mechanisms and support being constructed and arranged for successive relative movements first to present a supported shoe and said lasting mechanism in co-operative relation and then to present said shoe and the nailing mechanism in co-operative relation, and means for operating said lasting and nailing mechanisms in time relation to said successive relative movements of the shoe support and said mechanisms into co-operative relation.

8. A machine of the class described having, in combination, heel seat lasting mechanism, mechanism for nailing the heel end of the sole over the lasted heel seat, a shoe support, said mechanisms and support being constructed and arranged for successive relative movements first to present a supported shoe and said lasting mechanism in co-operative relation and then to present said shoe and the nailing mechanism in co-operative relation, and means actuated by presentation of the shoe and said mechanisms in co-operative relation for causing said mechanisms automatically to operate upon the shoe when presented.

9. A machine of the class described having, in combination, heel seat lasting mechanism, mechanism for nailing the heel end

of the sole over the lasted heel seat, a shoe support constructed and arranged for movements of determinate extent first to present the heel end of a supported shoe in co-operative relation to the lasting mechanism 70 and then to present the heel end of said shoe in co-operative relation to the nailing mechanism, and means for operating one of said mechanisms in time relation to the movement of said support to position a shoe 75 in co-operative relation to said mechanism.

10. A machine of the class described having, in combination, heel seat lasting mechanism, mechanism for nailing the heel end of the sole over the lasted heel seat, a shoe 80 support constructed and arranged for movements of determinate extent first to present the heel end of a supported shoe in co-operative relation to the lasting mechanism and then to present the heel end of said shoe 85 in co-operative relation to the nailing mechanism, and means for operating said mechanisms successively and in time relation to the successive movements of the shoe support to position the shoe in co-operative 90 relation to the respective mechanisms.

11. A machine of the class described having, in combination, a mechanism for lasting the heel seat of a turn shoe to the shank and forepart of which a sole has been sewed, 95 a device for holding the heel end of the sole turned back from the heel seat during the lasting, a mechanism for nailing the sole over the lasted heel seat, and a support movable to present the shoe in position for the 100 operation of the lasting mechanism and then for the operation of the nailing mechanism.

12. A machine of the class described having, in combination, a mechanism for lasting the heel seat of a turn shoe to the shank 105 and forepart of which a sole has been sewed, a mechanism for nailing the sole over the lasted heel seat, and a shoe support movable to position a shoe, whatever its size, 110 with its heel end in proper operative relation to the lasting mechanism and having a predetermined length of movement therefrom to carry the heel end of the shoe into similar relation to the nailing mechanism.

13. A machine of the class described having, in combination, a mechanism for lasting the heel seat of a turn shoe to the shank and forepart of which a sole has been sewed, a mechanism for nailing the sole over the lasted heel seat, a shoe support movable to 115 position a shoe, whatever its size, with its heel end in proper operative relation to the lasting mechanism, and means for giving the shoe support a measured length of movement from such position into predetermined 120 relation to the nailing mechanism.

14. A machine of the class described having, in combination, a mechanism for lasting the heel seat of a turn shoe to the shank and forepart of which a sole has been sewed, 125

1. a mechanism for nailing the sole over the lasted heel seat, a shoe support movable to position a shoe, whatever its size, with its heel end in proper operative relation to the lasting mechanism, including a carriage along which the shoe is initially moved to a predetermined position, means for locking the shoe in such position on said carriage, and means for imparting to the carriage, and means for imparting to the carriage, a predetermined movement to bring the support and its shoe into operative relation to the nailing mechanism.
2. A shoe machine having, in combination, two mechanisms for operating on a shoe successively, a shoe support having a movement of variable length relatively to one of said mechanisms to position shoes of different sizes in operative relation to said mechanism, and means for thereafter imparting to the support a movement automatically limited in extent to transfer the shoe to similar operative relation to the other mechanism.
3. A lasting and tacking and heel seat nailing machine having, in combination, a tacking mechanism, a nailing mechanism, and means for giving the shoe a predetermined length of movement from its position of operative relation to the tacking mechanism to a position of operative relation to the nailing mechanism whereby the nails and tacks are located in prearranged relation to each other.
4. A heel seat lasting and heel seat nailing machine having, in combination, heel seat lasting and heel seat nailing mechanisms, the lasting mechanism being open toward the nailing mechanism to receive a shoe heel-end foremost and the nailing mechanism presenting an open space under and beyond the nailing instrumentalities into which the shoe can be moved toe-end foremost to bring the heel seat under the nailing instrumentalities, a shoe support, and a guideway for directing movement of the support to present the shoe as described to said mechanisms successively.
5. A turn shoe heel seat lasting and heel seat nailing machine having, in combination, heel seat lasting and heel seat nailing mechanisms, the lasting mechanism being open toward the nailing mechanism to receive a shoe heel-end foremost and the nailing mechanism presenting an open space under and beyond the nailing instrumentalities into which the shoe can be moved toe-end foremost to bring the heel seat under the nailing instrumentalities, and means to turn the heel end of the sole up as the shoe is moved toward the lasting mechanism and to turn the said heel end of the sole down as a preliminary step to the nailing operation.
6. A heel seat lasting and heel seat nailing machine, having, in combination, heel seat lasting and heel seat nailing mechanisms, the lasting mechanism being open toward the nailing mechanism to receive a shoe heel-end foremost and the nailing mechanism presenting an open space under and beyond the nailing instrumentalities into which the shoe can be moved toe-end foremost to bring the heel seat under the nailing instrumentalities.
7. A heel seat lasting and heel seat nailing machine having, in combination, lasting and nailing mechanisms facing each other and constructed and arranged to permit a shoe by movements in the direction of its length to be thrust heel-end foremost into the lasting mechanism and then toe-end foremost toward the nailing mechanism to bring its heel end into operative relation to the nailing mechanism.
8. A heel seat lasting and heel seat nailing machine having, in combination, a lasting mechanism, a nailing mechanism, and a shoe guideway connecting the two mechanisms, said machine being constructed and arranged with the lasting and nailing mechanisms at opposite ends of the guideway and facing toward each other whereby the shoe thrust backwardly into the lasting mechanism will be brought into operative relation to the nailing mechanism by a reverse movement in the guideway.
9. A machine of the class described having, in combination, a heel seat nailing mechanism, means for operating the same, a shoe support, the machine being formed to present space under and back of the nailing mechanism into which the shoe mounted on said support can be moved toe-end first in moving the support and shoe to present the shoe to the seat nailing mechanism, and power operated means for thus moving the support and shoe and for thereafter moving them in the reverse direction from said mechanism.
10. A machine of the class described having, in combination, a heel seat nailing mechanism, means for operating the same, a shoe support, and a guideway for the support, the nailing mechanism being constructed and arranged to permit the shoe on said support to be presented under it toe-end foremost for nailing the heel seat and the guideway being arranged to direct the shoe into such relation to the nailing mechanism.
11. A machine of the class described having, in combination, a turn shoe heel seat lasting mechanism, means for operating said mechanism to last the heel seat after the sole has been sewed to the forepart and shank of the shoe, and a member extending in substantially perpendicular relation to the heel seat and operating automatically to turn the heel end of the sole out of the

way of the lasting mechanism as the shoe is moved into operative relation to the lasting mechanism.

25. A machine of the class described having, in combination, a turn shoe heel seat lasting mechanism, a shoe support, a guideway for the support, and means positioned in the path of movement of the shoe on said support and arranged to turn the heel end of the sole out of the way of the lasting mechanism.

26. A machine of the class described having, in combination, a heel seat lasting mechanism, a mechanism for nailing the heel seat end of the sole, a shoe support movable between the said mechanisms, and means arranged in position to turn up the heel end of the sole automatically as the shoe is moved by the support into position to be lasted.

27. A machine of the class described having, in combination, a heel seat nailing mechanism and a shoe support relatively movable to bring the heel end of a supported shoe in co-operative relation to the nailing mechanism, and means for turning down upon the heel seat the heel end portion of the sole as a preliminary incident to the nailing of the sole to the heel seat.

28. A machine of the class described having, in combination, a heel seat lasting mechanism, a mechanism for nailing the heel seat end of the sole, a shoe support movable between the said mechanisms, and means arranged to turn down the heel end of the sole upon the lasted heel seat preparatory to nailing the sole.

29. A machine of the class described having, in combination, a turn shoe heel seat lasting mechanism, a mechanism for nailing the heel seat end of the sole, a shoe support movable between the said mechanisms, means arranged in position to turn up the heel end of the sole automatically as the shoe is moved by the support into position to be lasted, and means to turn the heel end of the sole down upon the lasted heel seat preparatory to nailing the sole.

30. A machine of the class described having, in combination, a heel seat lasting mechanism, a mechanism for nailing the heel seat end of the sole, a shoe support, means for effecting relative movement of said mechanisms and said support to present the support and the lasting mechanism first in operative relation and then the support and the nailing mechanism in operative relation, and means for operating the lasting and the nailing mechanisms.

31. A machine of the class described having, in combination, a heel seat lasting mechanism, a mechanism for nailing the heel seat end of the sole, a guideway connecting said mechanisms, and a shoe support mounted to move along the guideway

between said mechanisms and arranged to present the shoe heel-end first in the lasting mechanism and to move the shoe toe-end first into operative relation to the nailing mechanism.

32. A machine of the class described having, in combination, a heel seat lasting mechanism, a mechanism for nailing the heel seat end of the sole, a guideway connecting said mechanisms, a shoe support mounted to move along the guideway between said mechanisms, and operating mechanism for causing the lasting and the nailing to be successively performed upon the shoe.

33. A machine of the class described having, in combination, a heel seat lasting mechanism, a mechanism for nailing the heel seat end of the sole, a guideway connecting said mechanisms, a shoe support mounted to move along the guideway between said mechanisms, and operating mechanism for causing the lasting and the nailing to be successively performed upon the shoe, the machine having space between the lasting and nailing mechanisms in excess of the length of the shoe to permit the jacking and unjacking of the shoe.

34. An organized machine of the class described having, in combination, spaced heel seat lasting and heel seat nailing mechanisms, a shoe support, power operated mechanism for moving said support to present a shoe first in co-operative relation to the lasting mechanism and then in co-operative relation to said nailing mechanism, and means for operating said mechanisms.

35. An organized machine of the class described having, in combination, spaced heel seat lasting and heel seat nailing mechanisms, a shoe support, power operated mechanism to move said support from a last and shoe receiving position intermediate of said mechanisms to present a supported shoe first to the lasting mechanism, then to present the supported shoe with its lasted heel seat in co-operative relation to the nailing mechanism and then to return said support to intermediate shoe receiving position, and means for operating said lasting and nailing mechanisms.

36. An organized machine of the class described having, in combination, spaced heel seat lasting mechanism and heel seat nailing mechanism and a shoe support relatively movable first to present the heel end of a supported shoe and said lasting mechanism in co-operative relation and then to present said heel end in co-operative relation to the nailing mechanism, and power operated means for effecting successively said relative movements of the shoe support and the lasting and nailing mechanisms and for automatically operating said mechanisms in time relation to said relative movements,

37. An organized machine of the class described having, in combination, spaced heel seat lasting mechanism and heel seat nailing mechanism, a shoe support, and power operated means for moving said support from a last and shoe receiving position intermediate of said mechanisms successively to present the heel end of a supported shoe to said lasting and nailing mechanisms respectively and to return said support to its initial intermediate position and for successively operating said lasting and nailing mechanisms in time relation to the movements of said support to present the shoe in co-operative relation to said mechanisms.

38. An organized machine of the class described having, in combination, heel seat lasting mechanism, a mechanism spaced from said lasting mechanism for nailing the heel end of the sole to the lasted heel seat, a shoe support arranged for movements relatively to said mechanisms to present a supported shoe in cooperative relation to said lasting and nailing mechanisms, and means to cause one of said mechanisms to operate upon the shoe, said means being arranged to be actuated by the presentation of the shoe to said mechanism.

39. An organized machine of the class described having, in combination, heel seat lasting mechanism, a mechanism spaced from said lasting mechanism for nailing the heel end of the sole to the lasted heel seat, a shoe support arranged for movements relatively to said mechanisms to present a supported shoe in co-operative relation to said lasting and nailing mechanisms, and means to cause said mechanisms to operate upon the shoe as an incident to the presentation of the shoe to said mechanisms.

40. An organized machine of the class described having, in combination, heel seat lasting wiper mechanism, a second mechanism spaced therefrom for nailing the heel end of the sole to the lasted heel seat, a shoe support arranged for movements relatively to said mechanisms to present a supported shoe in co-operative relation to said lasting and nailing mechanisms, and actuating means responsive to movement of the support to cause said mechanisms to operate upon the supported shoe as an incident to the presentation of the shoe in co-operative relation to said mechanisms.

41. An organized machine of the class described having, in combination, heel seat lasting mechanism, nailing mechanism for nailing the heel end of the sole to a lasted heel seat, a guideway connecting said mechanisms, a shoe support movable in said guideway from a shoe receiving position intermediate of said mechanisms in different directions successively to present a supported shoe in co-operative relation to the lasting and nailing mechanisms, and operat-

ing means for said lasting and nailing mechanisms actuated as an incident to the movement of the shoe into co-operative relation to said mechanisms to cause said mechanisms successively to last and nail the heel seat of the shoe.

42. An organized machine of the class described having, in combination, heel seat lasting means including wiper mechanism and tacking mechanism, nailing mechanism spaced from said lasting means for nailing the heel end of the sole to the lasted heel seat, a shoe support movable from a shoe receiving position intermediate of said lasting means and nailing mechanism in different directions successively to present a supported shoe in co-operative relation to the lasting means and nailing mechanism, and operating means for the wiper mechanism, and the nailing mechanism actuated as an incident to movement of the shoe support to present the shoe in co-operative relation to said mechanisms.

43. An organized machine of the class described having, in combination, heel seat lasting mechanism, nailing mechanism for nailing the heel end of a sole to the lasted heel seat, a guideway connecting said mechanisms, a shoe supporting carriage, power operated means for moving said carriage in said guideway from a shoe receiving position intermediate of said mechanisms in different directions successively to present a supported shoe in co-operative relation to said mechanisms, and operating means for said lasting and nailing mechanisms arranged to be actuated as an incident to the movement of the carriage to present the shoe in co-operative relation to said mechanisms.

44. An organized machine of the class described having, in combination, spaced heel seat lasting and heel seat nailing instrumentalities, a shoe support, manually controlled power operated mechanism for effecting determinate relative movements of said support and instrumentalities to present the supported shoe and the lasting instrumentality first in co-operative relation and then to present said support and the nailing instrumentality in co-operative relation, and additional power operated means for operating the lasting and nailing instrumentalities.

45. An organized machine of the class described having, in combination, spaced heel seat lasting mechanism and heel seat nailing mechanism, the lasting mechanism being open toward the nailing mechanism to receive a shoe heel-end foremost and the nailing mechanism presenting a space under and beneath the nailing instrumentalities into which the shoe can be moved toe-end foremost to bring the heel seat under the nailing instrumentalities, a shoe supporting carriage mounted for movement to

bring a supported shoe into co-operative relation to said mechanisms, manually controlled power operated mechanism for determinately moving said carriage from a 5 shoe receiving position between said mechanisms to present the shoe successively in co-operative relation to the lasting and nailing mechanisms and then to return it to intermediate position, and means for operating 10 said lasting and nailing mechanisms.

46. An organized machine of the class described having, in combination, spaced heel seat lasting mechanism and heel seat nailing mechanism, the lasting mechanism 15 being open toward the nailing mechanism to receive a shoe heel-end foremost and the nailing mechanism presenting an open space under and beneath the nailing instrumentalities into which the shoe can be moved 20 toe-end foremost to bring the heel seat under the nailing instrumentalities, a guideway connecting said mechanisms, a shoe supporting carriage movable in said guideway, manually controlled power-operated 25 mechanism for determinately moving said carriage from a shoe-receiving position intermediate of said mechanisms to present a shoe successively in co-operative relation to the lasting and nailing mechanisms and then 30 to return it to intermediate shoe receiving position, and means for operating said mechanisms in time relation to the movements of said shoe carriage into co-operative relation to said mechanisms to cause said mechanisms successively to last the heel seat of 35 the shoe and to nail the heel end of the sole to the lasted heel seat.

47. A machine for use in making shoes having, in combination, a shoe support on 40 which a shoe may be prepared for the operation of nailing the heel end of the sole upon the heel seat, a gang nailing mechanism, and a guide along which the shoe support is movable to carry the shoe into position 45 for the gang nailing operation and then reversely from nailing position, said support being constructed and arranged to carry the shoe toe-end foremost under and into operative relation to the nailing mechanism.

50. 48. A machine for use in making shoes having, in combination, heel seat lasting means, a support for holding the shoe during the heel seat lasting operation, gang mechanism for nailing the heel end of the 55 sole over the lasted heel seat, and means for operating said mechanism, said machine being constructed and organized to present under and beyond the nailing mechanism a space into which the shoe and its support can be advanced toe-end foremost from lasting position under and into operative relation to the sole nailing mechanism.

49. A machine of the class described having, in combination, heel seat lasting mechanism, nailing mechanism for fastening the 60

heel end of the sole over the lasted heel seat, and a shoe support comprising a heel rest upon which the shoe can turn laterally to position right and left crooked lasts with the median lines of their heel parts in substantially the same relation to the median line of the lasting mechanism and a toe rest extended laterally toward opposite sides of the machine to afford support for the differently located foreparts of such shoes, said shoe support and said mechanisms being relatively movable to bring the shoe and said mechanisms into operative relations while the shoe remains in substantially the same position on its support. 70 75

50. A machine of the class described having, in combination, a heel seat nailing mechanism, a heel seat lasting mechanism, a shoe support comprising a heel post on which the shoe may swing laterally and a toe rest 80 which is arc-shaped to permit right and left shoes to be positioned with their heel parts in the same relation to the lasting mechanism and their foreparts in reverse lateral relations to the toe rest, and guiding 85 means along which the support is movable to carry the shoe to the nailing mechanism in the same angular relation to the machine which it occupied in the heel lasting mechanism. 90 95

51. A machine of the class described having, in combination, gang tacking mechanism, operating mechanism therefor, a heel embracing band, means projecting the band outwardly in front of the tacking mechanism, a shoe support, means for moving the shoe support to thrust the shoe heel end foremost into the band and for forcing the band backwardly while the shoe is moved into operative relation to the tacking mechanism, and devices operating to close the band about the heel during such backward movement. 100 105

52. A machine of the class described having, in combination, tacking mechanism, operating mechanism therefor, an end embracing band located in a plane below the tacking mechanism and normally projected forwardly from the position occupied by a shoe in receiving the action of the tacking mechanism and movable with the shoe backwardly, and devices for closing the band about the shoe end as it is moved backwardly. 110 115

53. A machine of the class described having, in combination, means for laying an upper into lasted position at the heel seat, a heel embracing band, means projecting the band normally into open position forwardly of the lasting means and permitting backward movement of the band with the 120 shoe, and devices for closing the band as an incident to its backward movement as the shoe is moved into operative relation to the heel seat lasting means. 125

54. A machine of the class described hav- 130

ing, in combination, means for laying an upper into lasted position at the heel seat, a heel embracing band, means projecting the band normally into open position forwardly of the lasting means, a shoe support movable to present the shoe to the band, levers connected with the band ends, and means between which and the levers a relative movement is produced to close the band by movement of the shoe backwardly with the band.

55. A machine of the class described having, in combination, means for laying an upper into lasted position at the heel seat, a heel embracing band, a member supporting the middle of the band, links connected with the ends of the band, levers connected with the links, a cam slot formed in each lever and crossing the slot in the other lever, a plunger carrying a member standing in said cam slots, means for moving a shoe backwardly into the band and the band backwardly in the machine, and a yielding abutment for the plunger adapted to effect closing of the band and then adapted to yield to permit a full stroke of the shoe moving means.

56. A machine of the class described having, in combination, means for laying an upper into lasted position at the heel seat, a heel embracing band, a member supporting the middle of the band, links connected with the ends of the band, levers connected with the links, a cam slot formed in each lever and crossing the slot in the other lever, a plunger carrying a member standing in said cam slots, and means engaging said plunger during backward movement of the band to move the plunger relatively to the levers to cause closing movement of the band about the heel end of the shoe.

57. A machine of the class described having, in combination, a heel embracing band, a shoe support, means holding the band yieldingly open, band closing means including a yielding abutment, and mechanism for moving the shoe support backwardly to thrust the shoe into the band and for then carrying the band into position to be closed by the action of said abutment, the abutment being arranged to yield when the closing has been completed for the particular shoe in the band.

58. A machine of the class described having, in combination, a heel embracing band, a shoe support, means holding the band yieldingly open, band closing means including an abutment, and means for moving the shoe support to thrust the shoe into the band and for then carrying the band into position to be closed by the action of the abutment.

59. A machine of the class described having, in combination, a heel embracing band, a shoe support, means for moving the shoe

support and the band backwardly, means to effect closing of the band through such backward movement of the support and the band, and means for automatically locking the closing means with the band in embracing relation to the shoe.

60. A machine of the class described having, in combination, a heel embracing band, a shoe support, means for moving the shoe support and the band backwardly, means including a plunger to effect closing of the band through such backward movement of the support and the band, and an eccentric friction lock for securing the plunger in band closing position.

61. A machine of the class described having, in combination, a heel embracing band, a shoe support, band closing means, means to effect operation of the closing means, and means independent of said operating means to lock the closing means with the band in heel embracing position.

62. A machine of the class described having, in combination, a heel embracing band, a shoe support, band closing means, means to effect operation of the closing means, means independent of said operating means to lock the closing means, means for lasting the heel seat of a turn shoe, and means for nailing down the heel end of the turn sole over the lasted heel seat, the means for closing and locking the band being constructed and arranged to permit the shoe to be moved into operative relation to said nailing means with the band closed and locked around the heel end of the shoe.

63. A machine of the class described having, in combination, a heel embracing band, a shoe support, band closing means, means to effect operation of the closing means, means independent of said operating means to lock the band in heel embracing position, and means for inserting fastenings into the shoe bottom, the fastening inserting means and the band closing and locking means being relatively constructed and arranged to permit the shoe and band to be moved together relatively to said fastening inserting means with the band closed and locked around the heel end of the shoe.

64. A machine of the class described having, in combination, a heel embracing band, a shoe support, band closing means, means to effect operation of the closing means, means independent of said operating means to lock the band in heel embracing position, and means for shaping the heel seat face of the shoe, said seat shaping means and the band closing and locking means being relatively constructed and arranged to permit the shoe and band to be moved together relatively to said shaping means with the band closed and locked around the heel end of the shoe.

65. A machine of the class described having, in combination, a heel embracing band, a shoe support, band closing means, means to effect operation of the closing means, 6 means independent of said operating means to lock the band in heel embracing position, and means for operating on the shoe, said last named means and the band closing and locking means being relatively constructed 10 and arranged to permit the shoe and band to be moved together relatively to the means for operating on the shoe with the band closed and locked around the heel end of the shoe.
66. A machine of the class described having, in combination, a heel embracing band, means operative through movement of a shoe and the band to close the band about the shoe, heel seat lasting means, and means 20 to effect movement of the shoe to cause closing of the band and to carry the shoe into the field of operation of the lasting means.
67. A machine of the class described having, in combination, a heel embracing band, means operative through movement of a shoe and the band to close the band about the shoe, heel seat lasting means, means to effect movement of the shoe to cause closing of the band and to carry the shoe into the field of operation of the lasting means, means to lock the band closed, and heel seat nailing mechanism, said shoe with the band locked around it being movable away 30 from the lasting mechanism and into operative relation to the nailing mechanism.
68. A machine of the class described having, in combination, means for lasting the heel seat of a turn shoe, means for nailing the heel end of the sole over the lasted heel seat, a shoe support movable to carry the shoe to the lasting mechanism, and means to move the shoe in the reverse direction into the nailing mechanism.
69. A machine of the class described having, in combination, means for lasting the heel seat of a turn shoe, a heel embracing band, means for nailing the heel end of the sole over the lasted heel seat, the shoe 40 with the band embracing the same being movable from lasting position into operative relation to the nailing means, and means for operating the nailing means.
70. A machine of the class described having, in combination, a shoe support, means for lasting the heel seat of a turn shoe supported thereon, and means for nailing the heel end of the sole over the lasted heel seat, the shoe support and the nailing means 50 being relatively movable into operative relation.
71. A machine of the class described having, in combination, means for lasting the heel seat of a turn shoe, a heel embracing band, means for nailing the heel end of the 60 sole over the lasted heel seat, the shoe with the band embracing the same and the nailing means being relatively movable into operative relation, and means for actuating the nailing means to nail the sole while the band holds the upper materials clamped around the side faces of the last.
72. A machine of the class described having, in combination, a shoe support, means for lasting the heel seat of a supported shoe, 70 means for pressing and nailing the heel end of the sole upon the lasted heel seat, the shoe support and the pressing and nailing means being constructed and arranged for relative movement into operative relation, and means for actuating the pressing and nailing means to shape the heel end of the sole upon the heel seat and to nail said end of the sole to the lasted heel seat.
73. A machine of the class described having, in combination, a shoe support, means for lasting the heel seat of a supported shoe, 75 a heel embracing band, means for pressing the heel end of the sole upon the lasted heel seat, the shoe support with the band embracing the shoe and the pressing means being constructed and arranged for relative movement into operative relation, and means for actuating the pressing means to shape the heel end of the sole upon the heel seat while the band holds the upper materials clamped against the side faces of the last.
74. A machine of the class described having, in combination, a shoe support, means 80 for lasting the heel seat of a supported shoe, means for clamping the heel end of the upper materials to the side faces of the last, means for pressing the heel end of the sole upon the lasted heel seat and for nailing said sole end to the heel seat, the shoe support with the heel end of the shoe upper clamped to the last and the pressing and nailing means being constructed and arranged for relative movement into operative relation, and means for actuating the pressing means prior to the nailing operation to shape the heel end of the sole upon the heel seat while the clamping means holds the upper against the side faces of the last.
75. A machine of the class described having, in combination, a shoe support, means for lasting the heel seat of a supported shoe, 90 means for clamping the heel end of the upper materials to the side faces of the last, means for pressing the heel end of the sole upon the lasted heel seat and for nailing said sole end to the heel seat, the shoe support with the heel end of the upper materials clamped to the side faces of the last and the pressing and nailing means being constructed and arranged for relative movement into operative relation, and means for operating the pressing and nailing means in time relation to cause the pressing means

to shape the heel end of the sole upon the heel seat as a preliminary incident to the nailing of the sole to the heel seat while the upper clamping means holds the upper 5 clamped to the side faces of the last.

76. A machine of the class described having, in combination, a shoe support, means for lasting the heel seat of a supported shoe, a heel-embracing band to clamp the heel end 10 of the upper materials to the side faces of the last, power-operated mechanism for pressing the heel end of the sole upon the lasted heel seat and for nailing said sole end to the heel seat in time relation, the 15 shoe support with the band maintained in embracing and clamping relation to the heel end of the upper and said pressing and nailing mechanism being constructed and arranged for relative movement into operative 20 relation, and means for actuating said power-operated pressing and nailing mechanism as an incident to the relative movement of the shoe support and said mechanism into operative relation.

77. A machine of the class described having, in combination, shoe end clamping and shoe end lasting mechanisms and a shoe support arranged for relative movement to position a supported shoe and said mechanisms in co-operative relation, and operating 30 means for said mechanisms automatically actuated to clamp and last the end of the shoe through and as an incident to said relative movement of the shoe support and 35 said mechanisms into co-operative relation.

78. A machine of the class described having, in combination, a heel embracing band and heel seat lasting mechanism and a shoe support constructed and arranged for relative movement to position the heel end of a supported shoe and said band and lasting mechanism in co-operative relation, and closing means for said band and operating means for said lasting mechanism automatically 40 actuated through and as an incident to said relative movement of the shoe support and the band and lasting mechanism into 45 co-operative relation.

79. A machine of the class described having, in combination, separate heel end clamping and heel seat lasting mechanisms, a shoe support constructed and arranged for movement to position the heel end of a supported shoe in co-operative relation to 50 said mechanisms, and operating means for said end clamping and seat lasting mechanisms automatically actuated by movement of said shoe support and as an incident to the movement of a supported shoe into 55 co-operative relation to said mechanisms.

80. A machine of the class described having, in combination, shoe end clamping and wiping means and a shoe support relatively movable to present a supported shoe and

said means in co-operative relation, and 65 operating devices for said end clamping and wiping means actuated by said relative movement first to clamp the end of the shoe and then to wipe the upper materials over the bottom of the shoe end. 70

81. A machine of the class described having, in combination, shoe end clamping means, shoe end lasting means, a shoe support movable to present a supported shoe in co-operative relation to said lasting 75 means, and operating means for said end clamping and lasting means actuated by movement of a supported shoe into co-operative relation to said lasting means.

82. A machine of the class described having, in combination, shoe end clamping means, shoe end lasting wipers, operating devices for said clamping means and wipers, and a shoe support movable with a supported shoe toward said wipers and effective to 85 actuate said operating devices first to clamp the end of the shoe and then to cause the wipers to operate upon the end of the clamped shoe.

83. A machine of the class described having, in combination, an end clamping band, end lasting wipers, a shoe support movable to present one end of a supported shoe to said band and wipers, and operating means for the band and wipers arranged to be 95 actuated successively in said movement of the shoe support.

84. A machine of the class described having, in combination, shoe end clamping and lasting means and a shoe support relatively 100 movable to present a supported shoe and said means in co-operative relation, power operated means for effecting said relative movement of the shoe support and said means, and operating devices for said 105 clamping and lasting means actuated in time relation to said relative movement to clamp the end of the shoe and then to last said end.

85. A machine of the class described having, in combination, end clamping means, end lasting wipers, a shoe support, power operated means for moving said support to present a supported shoe in co-operative 110 relation to the clamping means and wipers, and operating devices for the clamping means and wipers actuated by said movement of the support first to clamp the end of the supported shoe and then to last said end. 115

86. A machine of the class described having, in combination, a heel end clamping band, heel seat lasting wipers, a shoe support arranged for movement to present the heel end of a supported shoe in co-operative 120 relation to said band and wipers, and means automatically operated to close said band and to actuate said wipers to last the heel 125

seat through movement of said shoe support incidental to presentation of the supported shoe in co-operative relation to said wipers.

87. A machine of the class described having, in combination, shoe end wiping and tacking mechanisms and a shoe support arranged for relative movement to position said mechanisms and a supported shoe in co-operative relation, and means for automatically operating said wiping mechanism through and as an incident to the relative movement of the support and said mechanisms to present a supported shoe and said mechanisms in co-operative relation.

88. A machine of the class described having, in combination, shoe end wiping and tacking mechanisms and a shoe support arranged for relative movement to position said mechanisms and a supported shoe in co-operative relation, and means for automatically operating said wiping mechanism and for automatically conditioning said tacking mechanism for tack driving through and as an incident to the relative movement of the support and said mechanisms to present a supported shoe and said mechanisms in co-operative relation.

89. A machine of the class described having, in combination, heel seat lasting mechanism, a shoe support, power operated means to move said support to position a supported shoe with its heel end in co-operative relation to said mechanism, and operating means for the seat lasting mechanism automatically actuated to last the heel seat through said power effected movement of the shoe support and as an incident to presentation of the shoe in co-operative relation to said lasting mechanism.

90. A machine of the class described having, in combination, a shoe support and end embracing wiper plates arranged for relative movement to cause the wiper plates to overwipe the upper at the extremity of the shoe, and means to cause said plates to swing inwardly over the edges of the shoe bottom at the sides of said end with a lengthwise component of movement in the direction of said extremity of the shoe.

91. A machine of the class described having, in combination, a shoe support and end embracing wiper plates arranged for relative movement with the wiper plates in open position to cause the portions of the wiper plates alined with the extremity of the shoe end to overwipe the upper at said extremity, and means to cause said plates to swing inwardly over the edges of the shoe bottom at the sides of said end with a lengthwise component of movement in the direction of said extremity of the shoe.

92. A machine of the class described having, in combination, a shoe support and end embracing wiper plates arranged for relative movement with the wiper plates in open

position to cause the portions of the wiper plates alined with the extremity of the shoe end to overwipe the upper at said extremity, and means for varying the extent of movement of said wipers over the edge of the shoe bottom.

93. A machine of the class described having, in combination, a shoe support and end embracing wiper plates arranged for relative movement with the wiper plates in open position to cause the portions of the wiper plates alined with the extremity of the shoe end to overwipe the upper at said extremity, and means operative at a predetermined point in said overwiping movement automatically to cause said plates to swing inwardly over the edges of the shoe bottom at the sides of said end with a lengthwise component of movement in the direction of said extremity of the shoe.

94. A machine of the class described having, in combination, a shoe support and end embracing wiper plates arranged for relative movement with the wiper plates in open position to cause the abutting end portions of the plates to wipe the upper over the edge of the shoe bottom at the extremity of the shoe end, means to arrest said relative overwiping movement and to cause said wiper plates to swing inwardly over the edges of the shoe bottom at the sides of said end of the shoe, and means for variably predetermining the extent of inward swinging movement of said wiper plates.

95. A machine of the class described having, in combination, wipers comprising end embracing wiper plates having their closed end portion supported for movement lengthwise of the shoe and mounted for swinging movement about shifting fulcrum points in approximate alinement with the closed end portion of the wipers, a shoe support movable to cause the extremity of an end of the shoe to engage and be overwiped by said end portion of the wipers, and means operative to move said end portion of the wipers longitudinally with the shoe to cause said wipers to swing in over the sides of the shoe bottom.

96. A machine of the class described having, in combination, a shoe support, wipers comprising end embracing wiper plates normally outspread and having fulcrum arms laterally extended in approximate alinement with the closed end of the wipers, a member connected to the portions of said plates at the extremity of one end of a supported shoe and arranged for movement with said plates longitudinally of the shoe to swing said plates on said fulcrum arms inwardly over the sides of the shoe bottom at said end of the shoe, the shoe support being movable relatively to the wipers to bring one end of a shoe into co-operative relation to said wipers and to cause the portions of the wip-

- ers at the extremity of the shoe end to over-
wipe the upper at said extremity, and means
operative at a determinate point in said
overwiping movement to move said member
5 longitudinally of the shoe to swing said
wiper plates inwardly over the sides of the
shoe bottom at said end of the shoe.
97. A machine of the class described hav-
ing, in combination, a shoe support, wipers
10 comprising end embracing wiper plates
normally outspread and having fulcrum
arms laterally extended in approximate
alinement with the closed end of the wipers,
a member connected to the portions of said
15 plates at the extremity of one end of a
supported shoe and arranged for movement
with said plates longitudinally of the shoe
to swing said plates on said fulcrum arms
inwardly over the sides of the shoe bottom
20 at said end of the shoe, the shoe support
being movable relatively to the wipers to
bring one end of a shoe into co-operative
relation to said wipers and to cause the por-
tions of the wipers at the extremity of the
25 shoe end to overwipe the upper at said ex-
tremity, means operative at a determinate
point in said overwiping movement to move
said member longitudinally of the shoe to
swing said wiper plates inwardly over the
30 sides of the shoe bottom at said end of the
shoe, and means for determinately limit-
ing the extent of inwardly swinging move-
ment of said wiper plates.
98. A machine of the class described hav-
35 ing, in combination, end embracing wiper
plates mounted to turn about shifting ful-
crum points, an operating member pivotal-
ly connected to the adjacent ends of the
plates and mounted for movement in a di-
40 rection longitudinally of said plates, a shoe
support, means for effecting relative move-
ment of said support and wiper plates to
cause said plates to embrace one end of a
supported shoe and to overwipe the upper
45 at the extremity of said end, and means for
automatically actuating said operating
member as an incident to said overwiping
movement to swing said plates inwardly
over the sides of the shoe bottom at said end
50 of the shoe.
99. A machine of the class described hav-
ing, in combination, wipers comprising end
embracing wiper plates mounted to turn
about shifting fulcrum points remote from
55 the forward open end of the wipers, an op-
erating member pivotally connected to the
rear closed end of the wipers and mounted
for movement in a direction longitudinally
of said plates, a shoe support, means for
60 effecting relative movement of said support
and wiper plates to cause said plates to em-
brace one end of a supported shoe and
to overwipe the upper at the extremity of
said end of the shoe, and means for engag-
65 ing and automatically moving said plate-
- connected operating member as an inci-
dent to said relative overwiping movement
to swing said plates inwardly over the sides
of the shoe bottom at said end of the shoe.
100. A machine of the class described hav-
ing, in combination, wipers comprising end
embracing wiper plates mounted to turn
about shifting fulcrum points, an operating
member pivotally connected to the closed end
70 of said wipers and mounted for movement
in a direction longitudinally of said plates,
a shoe support, means for effecting rela-
tive movement of said support and wiper
plates to cause said plates to embrace one
75 end of a supported shoe and to overwipe the
upper at the extremity of said end, an abut-
ment on said operating member and an
aligned abutment on said shoe support ar-
ranged to contact at a determinate point in
80 said overwiping movement to limit the ex-
tent of overwipe at said extremity and to
move said operating member to swing said
wiper plates inwardly over the sides of the
shoe bottom at said end of the shoe.
101. A machine of the class described hav-
ing, in combination, wipers comprising end
embracing wiper plates mounted to turn
about shifting fulcrum points, an operating
member pivotally connected to the closed
85 end of said wipers and mounted for move-
ment in a direction longitudinally of said
plates, a shoe support, means for effecting
relative movement of said support and
wiper plates to cause said plates to embrace
90 one end of a supported shoe and to over-
wipe the upper at the extremity of said end,
an adjustable abutment on said operating
member and an aligned abutment on said
shoe support arranged to contact at a point
95 during said relative overwiping movement
determinately to limit the extent of said
overwiping movement and to move said op-
erating member to swing said wiper plates
inwardly over the sides of the shoe bottom
100 at said end of the shoe, and an adjustable
stop member arranged to co-operate with
said operating member, when so moved,
determinately to limit the extent of said
inward swinging movement of the wiper
105 plates.
102. A machine of the class described hav-
ing, in combination, a shoe support and end
lasting mechanism arranged for relative
movement, power operated means for effect-
ing determinate relative movement of said
110 support and mechanism to present a sup-
ported shoe and said mechanism in co-op-
erative relation, and operating means for
said lasting mechanism automatically actu-
ated in said relative movement by engage-
115 ment with the shoe support.
103. A machine of the class described hav-
ing, in combination, a shoe support, end
lasting wipers, power operated means for
120 effecting determinate movement of said sup-
125 port and wipers, and a shoe support and
lasting mechanism arranged for relative
movement, power operated means for effect-
ing determinate relative movement of said
support and mechanism to present a sup-
130 ported shoe and said mechanism in co-op-
erative relation, and operating means for
said lasting mechanism automatically actu-
ated in said relative movement by engage-
ment with the shoe support.

- port to present one end of a supported shoe in co-operative relation to said wipers, and operating means for said wipers automatically actuated through said movement of the support to cause the wipers to wipe the upper materials over the bottom of the shoe. 65
- 5 104. A machine of the class described having, in combination, a shoe support, heel seat lasting wipers, power operated means for effecting determinate movement of the support to present the heel seat of a supported shoe in co-operative relation to the wipers, and wiper closing means actuated by said movement of the shoe support. 70
- 10 105. A machine of the class described having, in combination, a shoe support, end embracing wiper members having a series of tacking mechanisms permanently incorporated therein and positioned in determinate relation to their wiping edges, and means to operate said wiper members including a device for adjustably limiting their overwiping movement to determine the positions of the tacks. 75
- 20 106. A machine of the class described having, in combination, a shoe support and end embracing wiper members relatively movable to wipe the upper materials over the edge of the bottom of a supported shoe at one end of the shoe, said wiper members having a series of tacking mechanisms permanently incorporated therewith and positioned in determinate relation to their wiping edges, and means operated by the relative movement of said shoe support and wiper members for feeding tacks to said mechanisms. 80
- 30 107. A machine of the class described having, in combination, a shoe support and end embracing wiper members relatively movable to wipe the upper materials over the edge of the bottom of a supported shoe lengthwise and laterally of the shoe, said wiper members having a series of tacking mechanisms permanently incorporated therewith and positioned in determinate relation to the wiping edges of said members and arranged to drive tacks through their wiping faces into the wiped-over upper materials, and means for separately adjusting the limits of relative movement of the shoe support and the wiper members lengthwise and laterally of the shoe to determine the positions of the different tacks. 85
- 40 108. A machine of the class described having, in combination, a shoe support and complementary curved end-embracing wiper members relatively movable to wipe the upper materials over the edge of the bottom of a supported shoe at one end of the shoe, said wiper members having body portions extending substantially perpendicularly to their wiping faces with a series of tacking mechanisms permanently incorporated with said body portions of the members and extending along said members in determinate relation to their wiping edges, and members projecting laterally outward from said perpendicularly extending portions of the wiper members to provide fulcrum arms for closing the wipers over a shoe. 90
- 50 109. A machine of the class described having, in combination, a shoe support and end embracing wiper members relatively movable to wipe the upper materials over the edge of the bottom of a supported shoe at one end of the shoe, said wiper members having a gang tacking mechanism permanently incorporated therewith, and means operative in time relation to other parts of the machine for feeding loose tacks to said mechanism. 95
- 60 110. A machine of the class described having, in combination, a shoe support, end embracing wiper members mounted to close over one end of a shoe bottom and having permanently incorporated therewith a gang of tacking mechanisms, power operated means for effecting a relative movement of said support and wiper members to cause said members to wipe the edge of the shoe upper over the bottom of a supported shoe and to position said tacking mechanisms in determinate relation to the wiped over shoe upper materials, and means automatically operative to limit said relative movement of the shoe support and the wiper members and adjustable to vary the limit of such relative movement. 100
- 70 111. A machine of the class described having, in combination, a shoe support and end embracing wiper members relatively movable to wipe shoe upper material over the edge of the shoe bottom at one end of a supported shoe, said wiper members having a series of tack blocks in their lower wiping faces and having body portions extending upwardly from said wiping faces with a series of tack drivers and complementary tack feeding passages therein co-operating with said series of tack blocks. 105
- 80 112. A machine of the class described having, in combination, a shoe support, end embracing wiper members mounted to close over one end of a shoe bottom and having permanently incorporated therewith a gang of tacking mechanisms in determinate relation to their wiping edges, power operated means for effecting relative movement of the shoe support and end wiper members to cause said members to wipe shoe upper materials over the bottom of a supported shoe at one end and to position said tacking mechanisms in co-operative relation to the wiped over shoe upper materials, additional power means for operating said tacking mechanisms to drive tacks through the wiped over upper materials, and mechanism 110
- 90 113. A machine of the class described having, in combination, a shoe support, end embracing wiper members mounted to close over one end of a shoe bottom and having permanently incorporated therewith a gang of tacking mechanisms in determinate relation to their wiping edges, power operated means for effecting relative movement of the shoe support and end wiper members to cause said members to wipe shoe upper materials over the bottom of a supported shoe at one end and to position said tacking mechanisms in co-operative relation to the wiped over shoe upper materials, additional power means for operating said tacking mechanisms to drive tacks through the wiped over upper materials, and mechanism 115
- 100 114. A machine of the class described having, in combination, a shoe support, end embracing wiper members mounted to close over one end of a shoe bottom and having permanently incorporated therewith a gang of tacking mechanisms in determinate relation to their wiping edges, power operated means for effecting relative movement of the shoe support and end wiper members to cause said members to wipe shoe upper materials over the bottom of a supported shoe at one end and to position said tacking mechanisms in co-operative relation to the wiped over shoe upper materials, additional power means for operating said tacking mechanisms to drive tacks through the wiped over upper materials, and mechanism 120
- 110 115. A machine of the class described having, in combination, a shoe support, end embracing wiper members mounted to close over one end of a shoe bottom and having permanently incorporated therewith a gang of tacking mechanisms in determinate relation to their wiping edges, power operated means for effecting relative movement of the shoe support and end wiper members to cause said members to wipe shoe upper materials over the bottom of a supported shoe at one end and to position said tacking mechanisms in co-operative relation to the wiped over shoe upper materials, additional power means for operating said tacking mechanisms to drive tacks through the wiped over upper materials, and mechanism 125

automatically operative to bring the machine to a stop between the overwiping operation and the tacking operation.

113. A machine of the class described
 5 having, in combination, a shoe support, end embracing wiper members having body portions extending upwardly from their wiping faces and having a series of tack blocks at their wiping faces with co-operating tack
 10 feeding and driving means in said upwardly extending body portions, and means for effecting relative movement of said support and wiper members to cause said members to wipe the upper materials over the edge of
 15 the shoe bottom at one end of the shoe and to position the tack blocks and tacks in co-operative relation to the wiped over edge of the upper materials.
114. A machine of the class described
 20 having, in combination, end embracing wiper members having a series of tack blocks extending along their wiping faces and having body portions extending upwardly from said wiping faces and provided
 25 with a series of tack drivers and complementary tack feeding passages co-operating with said tack blocks, a shoe support, means for relatively moving said support and wiper members to cause said members to
 30 overwipe the upper materials at one end of a supported shoe and to position said tack blocks in co-operative relation to the overwiped edge of the upper, and means whereby said tack drivers may be operated to
 35 drive tacks from said blocks into the overwiped upper.

115. A machine of the class described having, in combination, a shoe support, end embracing wipers having a gang of tacking mechanisms permanently incorporated therewith, means for moving said support to bring one end of a supported shoe into co-operative relation to the wipers, means operative in the course of said movement of
 40 the shoe support for feeding tacks to said tacking mechanisms, means for closing said wipers over the bottom of said end of the shoe to overwipe the shoe upper materials and to position the tacking mechanisms in
 45 co-operative relation to the overwiped upper materials, and means for operating the tacking mechanisms.

116. A machine of the class described having, in combination, a shoe support, end
 55 embracing wipers having a gang of tacking mechanisms permanently incorporated therewith and arranged to drive a series of tacks through the wiping faces of said wipers at determinate distances from and
 60 along their wiping edges, means for effecting relative movement of said support and wipers to cause the wipers to wipe the upper over the bottom of one end of a supported shoe and to position said tacking
 65 mechanisms in co-operative relation to the

overwiped edge of the upper, and means for adjustably limiting the extent of movement of said wipers over the edge of the shoe bottom.

117. A machine of the class described
 70 having, in combination, a shoe support, end embracing wiper members having permanently incorporated therewith a gang of tacking mechanisms extending along said members and arranged to drive a line of
 75 tacks through the wiping faces of said members at determinate distances from their wiping edges, power operated means for effecting an automatically limited closing movement of said members over the edge of
 80 the shoe bottom at one end to overwipe the upper and to position said tacking mechanisms in co-operative relation to the overwiped edge of the upper, power controlled means for feeding tacks to said mechanisms, and separately controlled power operated means for driving said tacks substantially simultaneously into the overwiped portion
 85 of the upper material.

118. In a machine of the class described, end embracing wiper members having a series of tacking mechanisms permanently incorporated therewith, said members having body portions extending substantially perpendicularly to the plane of the shoe bottom and affording support for said tacking mechanisms, and spring means between said body portions of the members acting to separate them laterally of the shoe.

119. In a machine of the class described, end embracing wiper members having a series of tack blocks permanently incorporated therewith and extending along their wiping faces in determinate relation to their wiping edges, tack drivers carried by said members, and a driving plate arranged to overlie the ends of the drivers and relatively to which the drivers are movable over the shoe with said wiper members.

120. In a machine of the class described, end embracing wiper members having a series of tack blocks permanently incorporated therewith and extending along their wiping faces in determinate relation to the wiping edges, said members having body portions extending upwardly from their wiping faces and provided with a series of tack feeding channels and tack driving members co-operating with said tack blocks.

121. A machine of the class described having, in combination, two mechanisms for operating successively upon a shoe arranged in spaced opposed relation, a shoe supporting carriage mounted for movement from a shoe-receiving position intermediate of said mechanisms to present a shoe successively to the operation of said mechanisms, means for automatically locking a shoe in
 125 the position on its carriage when presented in
 130

- position for the operation of the first of said mechanisms, and means for automatically releasing the locking means when the carriage is returned from co-operative relation to the second of said mechanisms to initial intermediate shoe receiving position.
122. A machine of the class described having, in combination, two mechanisms for operating successively upon a shoe arranged in spaced and opposed relation, a carriage mounted for movement from a shoe-receiving position intermediate of said mechanisms to present a supported shoe successively to the operations of said mechanisms,
- 10 123. A machine of the class described having, in combination, a mechanism for inserting fastenings in shoe out soles and a shoe support relatively movable to position a supported shoe and said mechanism in co-operative relation, a pressure member movable perpendicularly relatively to the shoe bottom and constructed and arranged to apply conforming pressure to the sole preparatory to inserting the fastenings, and power means arranged to be operated in time relation to the relative movement of said mechanism and shoe support to cause said member to apply pressure to the sole.
- 15 124. A machine of the class described having, in combination, a mechanism for inserting fastenings in shoe out soles, a shoe support movable lengthwise of the shoe to position a supported shoe in co-operative relation to said mechanism, means for applying conforming pressure to the sole preparatory to inserting the fastenings, and power means arranged to be actuated by movement of the shoe support to impart operative movement to said pressure applying means.
- 20 125. A machine of the class described having, in combination, mechanism for lasting a portion of a shoe, an opposed mechanism spaced therefrom for fastening the sole down on the lasted portion, a carriage movable from a shoe-receiving position intermediate of said mechanisms to present a supported shoe successively to the action of the lasting and sole fastening mechanisms, a shoe support movable relatively to and with said carriage to position a shoe for co-operation with the lasting mechanism, means arranged automatically to lock said support in position on said carriage during the successive operations of said lasting and fastening mechanisms, and means automatically to release said locking means when the carriage is returned to initial intermediate shoe-receiving position.
- 25 126. A machine of the class described having, in combination, a mechanism for inserting fastenings in shoe out soles, a shoe support movable lengthwise of the shoe to position a supported shoe in co-operative relation to said mechanism, means for applying conforming pressure to the sole preparatory to inserting the fastenings, and power means arranged to be actuated by movement of the shoe support to impart operative movement to said pressure applying means.
- 30 127. A machine of the class described having, in combination, a sole nailing mechanism and a shoe support relatively movable to position a supported shoe and said nailing mechanism in co-operative relation, and pressure applying means arranged to be actuated by said relative movement of the support and nailing mechanism to engage and force down on the bottom of the shoe under conforming pressure the portion of the sole to be nailed.
- 35 128. A machine of the class described having, in combination, mechanism for nailing one end of a shoe sole to the lasted end of a shoe and a shoe support relatively movable into co-operative relation, and means automatically operative to apply conforming pressure to the sole on the bottom of said lasted shoe end preparatory to the nailing operation and as an incident to the relative movement of the support and nailing mechanism into co-operative relation.
- 40 129. A machine of the class described having, in combination, sole pressing and sole nailing mechanisms and a shoe support relatively movable into co-operative relation, and operating means for said mechanisms responsive to said relative movement of the shoe support and said mechanisms automatically to cause the sole pressing and sole nailing operations to occur successively.
- 45 130. A machine of the class described having, in combination, a sole pressing member having a nail holding block in its pressure applying face and a shoe support relatively movable into co-operative relation, means for operating said member to apply conforming pressure to the shoe sole, and means for driving a nail through the pressure face of said block into the sole.
- 50 131. A machine of the class described having, in combination, a mechanism for in-

ing, in combination, sole pressing and sole nail mechanisms and a shoe support relatively movable into co-operative relation, and power means for operating said mechanisms in time relation responsive to said relative movement of the support and mechanisms into co-operative relation.

132. A machine of the class described having, in combination, mechanism to press the heel end of a sole into conformation to a lasted heel seat, mechanism for driving a plurality of nails into the conformed heel end of the sole, a shoe support movable to present the heel end of a lasted shoe in co-operative relation to said mechanisms, and means responsive to said movement of the support into co-operative position for causing the pressing and nailing mechanisms successively to operate upon the heel end of the sole of the supported shoe.

133. A machine of the class described having, in combination, mechanism to press the heel end of a sole into conformation with a lasted heel seat, mechanism for driving a plurality of nails into the conformed heel end of the sole, a shoe support movable to present the heel end of a lasted shoe in co-operative relation to said mechanisms, and power operated means actuated as an incident to the movement of said support into co-operative relation to said mechanisms to cause the pressing and nailing mechanisms to operate upon the heel end of the sole of the supported shoe successively and in time relation.

134. A machine of the class described having, in combination, nailing mechanism including a nailing head movable to engage and press the heel end of a sole into conformation to the lasted heel seat of a shoe, a shoe support movable to present the heel end of the sole of a lasted shoe in co-operative relation to said head, and means responsive to said movement of the support to cause said head to engage and press down on the heel seat the heel end of the sole of the presented shoe preparatory to the nailing of the sole.

135. A machine of the class described having, in combination, a gang nailing mechanism including a nailing head for supporting the nails movable to engage and press the heel end of a sole into conformation to the lasted heel seat of a shoe, a shoe support movable to present the heel end of the sole of a lasted shoe in co-operative relation to said head, and power means for operating said nailing mechanism to cause said head to apply conforming pressure to the sole in time relation and prior to the driving of the nails in the sole.

136. A machine of the class described having, in combination, a nailing head mounted for movement to cause one face to engage and press a sole into conformation to the

lasted bottom of a shoe, said nailing head having a plurality of nail blocks in its pressure face and co-operating nail feeding and driving passages therein, a nail driving member having drivers co-operating with said driving passages and relatively to which said nailing head is movable in conforming the sole to the shoe bottom, a shoe support movable to present the heel end of the sole of a supported shoe in co-operative relation to said nailing head, and means for successively causing said nailing head to conform the sole of a positioned shoe and said driving member to drive nails through said head into the conformed sole.

137. A machine of the class described having, in combination, a power-operated mechanism for acting upon a shoe, a guideway leading to said mechanism, a shoe support movable in said guideway to present a supported shoe in co-operative relation to said mechanism, and starting means for said power-operated mechanism responsive to movement of said guided shoe support into co-operative relation to said mechanism.

138. A machine of the class described having, in combination, a power operated gang nailing mechanism and a shoe support relatively movable to position the sole of a supported shoe and said mechanism in co-operative relation, and starting means for said power operated mechanism actuated as an incident to said relative movement of the support and mechanism into co-operative relation.

139. A machine of the class described having, in combination, mechanism to press a shoe sole into conformation to the lasted bottom of a shoe, mechanism for nailing the pressed sole portion of the shoe, power operated means for causing said pressing and nailing mechanisms successively to operate in time relation, a shoe support movable to present the sole of a supported shoe in co-operative relation to said mechanisms, and starting means for said power-operated means responsive to movement of the shoe support into co-operative relation to said mechanisms.

140. A machine of the class described having, in combination, a power operated nailing mechanism, a clutch for operating said mechanism, a shoe support movable to present a supported shoe in co-operative relation to said nailing mechanism, and controlling means for said clutch responsive to movement of said support in the direction to present the shoe in operative relation to said mechanism.

141. A machine of the class described having, in combination, mechanism for pressing a shoe sole into conformation to the lasted bottom of a supported shoe, gang nailing mechanism arranged to nail the pressed sole, a shoe support movable to present the sole

of a supported shoe in cooperative relation to said mechanisms, power means for operating said sole pressing and nailing mechanisms successively in time relation, a clutch 5 for operating said power means, and controlling means for said clutch responsive to said movement of the shoe support.

142. A machine of the class described having, in combination, mechanism for nailing the heel end of a sole to the heel seat of a lasted shoe, clutch controlled power-driven operating means for said mechanism, a shoe support movable in a direction to position a supported shoe in co-operative relation to 10 said nailing mechanism, and clutch controlling means positioned in the path of said movement of the support and arranged for actuation to operate said mechanism in response to movement of said support in said 15 direction only.

143. A machine of the class described having, in combination, mechanism for pressing the heel end of a sole into conformation to the lasted heel seat of a supported shoe, mechanism for nailing the conformed heel 25 end of the sole to the shoe, a clutch-controlled power-driven shaft and operating connections to said mechanisms arranged to cause said pressing mechanism to operate 30 prior to and in time relation to the nailing mechanism, a shoe support movable to present the heel end of the sole of a lasted shoe in co-operative relation to said mechanisms, and clutch controlling means positioned in the path of said movement of the support and arranged for actuation to drive 35 said shaft in response to movement of said support in shoe positioning direction only.

144. A machine of the class described having, in combination, two spaced fastener inserting mechanisms, a work support guided for successive movements to present supported work successively to the action of said mechanisms, and means for feeding fasteners to said mechanisms operated responsive to movement of said work support.

145. A machine of the class described having, in combination, two spaced gang fastener inserting mechanisms arranged in opposed relation, a shoe support mounted for movement to present the bottom of a supported shoe successively in cooperative relation to said mechanisms, and means for feeding a gang of fasteners to an inserting mechanism automatically operated as an incident to movement of the work support into co-operative relation to a fastener inserting mechanism.

146. A machine of the class described having, in combination, spaced heel seat lasting and tacking and heel seat nailing mechanisms arranged in opposed relation, a guideway connecting said mechanisms, a shoe support movable in said guideway to present a supported shoe to the action of the

heel seat lasting and tacking mechanism and to the heel seat nailing mechanism successively, and means for feeding tacks and nails, respectively, to said mechanisms responsive to said movement of the shoe support.

147. A machine of the class described having, in combination, spaced gang fastener inserting mechanisms arranged in opposed relation and each including a fastener 75 separating and distributing mechanism, a shoe support guided for successive movements to present the same portion of a supported shoe successively in co-operative relation to said mechanisms, and means for automatically actuating both of said separating and distributing mechanisms substantially simultaneously and responsive to movement of said shoe support into co-operative relation to the first of said inserting 80 mechanisms to be operated.

148. A machine of the class described having, in combination, spaced gang fastener inserting mechanisms, arranged in opposed relation and each including a fastener 90 separating and feeding mechanism, a guideway connecting said inserting mechanisms, a shoe supporting carriage movable in said guideway from an intermediate shoe-receiving position to successive positions for presenting a supported shoe successively in co-operative relation to said mechanisms, a rock shaft, operating connections from said shaft to each of said fastener separating and distributing mechanisms, and means for rocking said shaft responsive to movement of the shoe carriage from said intermediate position to a position of co-operation with the first of said inserting mechanisms to operate 95 upon the shoe.

149. A machine of the class described having, in combination, shoe lasting mechanism, a shoe support arranged to position a shoe for the operation of said mechanism, and mechanism for nailing a sole to the shoe, said shoe support and sole nailing mechanism being relatively movable to present the shoe and said nailing mechanism in co-operative relation after the operation of the lasting mechanism on the shoe has been completed.

150. A machine of the class described having, in combination, shoe lasting mechanism, mechanism for securing a sole to the shoe, a shoe support, and power operated means for imparting to said shoe support an automatically limited movement to carry the shoe from lasting position and to present it in determinate relation to the sole securing mechanism.

151. A machine of the class described having, in combination, shoe lasting mechanism, power operated mechanism for securing a sole to the shoe, a shoe support movable to carry a shoe from lasting position and 130

to present it to the sole securing mechanism, and means operated by the movement of the shoe support for initiating the operation of said sole securing mechanism.

5 152. A machine of the class described having, in combination, shoe lasting mechanism, mechanism for securing a sole to the shoe, and a shoe support mounted for movement in one direction to present a shoe to the
10 lasting mechanism and in the opposite direction to present the shoe to the sole securing mechanism.

153. A machine of the class described having, in combination, shoe lasting mechanism comprising end embracing wipers, power operated mechanism for securing a sole to the shoe, a shoe support movable to present a shoe successively to said lasting mechanism and to said sole securing mechanism, means operated by movement of said shoe support for closing the wipers inwardly over the shoe, and means also operated by movement of the shoe support for initiating the operation of the sole securing mechanism.

154. A machine of the class described having, in combination, shoe lasting mechanism including tacking instrumentalities, power operated mechanism for nailing a sole to the shoe, a shoe support movable to present a shoe successively to said lasting and sole nailing mechanisms, means arranged to be rendered operative by movement of the shoe support to supply tacks and nails to said different mechanisms, and additional means arranged to be operated by movement of the shoe support to initiate the operation of said sole nailing mechanism.

40 of said sole nailing mechanism.

45 155. A machine of the class described having, in combination, shoe lasting mechanism, mechanism for securing a sole to the shoe, a movable shoe support, and power operated means arranged to be actuated successively by the operator for moving the shoe support to present the shoe in operative relation to the lasting mechanism and to the sole nailing mechanism respectively and to come automatically to a stop with the shoe in operative relation to each of said mechanisms.

50

156. A machine of the class described having, in combination, shoe lasting mechanism, mechanism for securing a sole to the shoe, a movable shoe support, and power operated means arranged to be actuated successively by the operator for moving the shoe support to present the shoe in operative relation to the lasting mechanism and to the sole nailing mechanism respectively and to come automatically to a stop with the shoe in operative relation to each of said mechanisms, said lasting mechanism including power operated tacking means arranged to be independently actuated while the shoe is in lasting position.

157. A machine of the class described having, in combination, shoe lasting mechanism; power operated mechanism for nailing a sole to the shoe, a movable shoe support, power operated means arranged to be actuated successively by the operator for moving said support to present the shoe in operative relation to the different respective mechanisms and to come automatically to a stop with the shoe in operative relation to each of said mechanisms, and means arranged to be operated by movement of the shoe support toward sole nailing position for initiating the operation of the nailing mechanism.

158. In a machine of the class described, the combination with mechanism for operating on a shoe, of means arranged for clamping engagement with the opposite sides of an end portion of the shoe, said clamping means being movable with the shoe into operative relation to said mechanism, and a device arranged to be operated by said movement of the clamping means and the shoe to close said clamping means inward laterally of the shoe. 85 90

ward laterally of the shoe. 159. In a machine of the class described, the combination with mechanism for operating on a shoe, of a shoe end embracing band and a support for said band mounted 95 for movement with a shoe into operative relation to said mechanism, a device on said support for closing the band about the shoe, and an abutment for engaging said device and operating it through said movement of 100 the band and the shoe.

160. In a machine of the class described, the combination with mechanism for operating on a shoe, of a shoe end embracing band and a support for said band mounted for movement with a shoe into operative relation to said mechanism, a spring controlled member on said support connected to the band and arranged to hold it normally open laterally of the shoe, and an abutment for engaging said member and operating it to close the band through said movement of the band and the shoe, said abutment being yieldable to permit continued movement of the shoe and the band after the band has been closed about the shoe. 105 110 115

161. In a machine of the class described, a shoe end embracing band and a support for said band mounted for movement with a shoe in different directions to present the shoe in different positions, closing means for the band arranged to be operated by movement of the shoe and the band in one direction, means automatically operative to lock the band in closed position and to hold it locked as the shoe and the band are moved in a different direction to present the shoe in another position, and means automatically operative upon movement of the shoe and 120 125 130

the band from said last named position to cause said locking means to release the band.

162. In a machine of the class described, a shoe end embracing band, means for jacking a shoe into said band, means for locking the shoe in the band, the shoe and the band being movable together to present the shoe in an operating position and subsequently to return the shoe from said position, and 10 means automatically operative in such return of the shoe to cause said locking means to release the shoe.

163. In a machine of the class described, a shoe support and a wiper support mounted for relative movement in a direction lengthwise of the shoe, end embracing wipers constructed and arranged to extend substantially continuously round the end and along the opposite sides of the end portion 20 of the shoe, said wipers having pin and slot connections with the wiper support to permit them to swing laterally of the shoe about different axes laterally displaced from the longitudinal median line of the 25 shoe, and means arranged to be operated by the relative movement of said shoe support and wiper support to close the wipers inwardly over the shoe about said axes.

164. In a machine of the class described, 30 a shoe support and a wiper support mounted for relative movement in a direction lengthwise of the shoe, end embracing wipers mounted on said wiper support for closing movement laterally of the shoe about 35 different axes laterally displaced from the longitudinal median line of the shoe, and a device connected to said wipers substantially midway between the opposite sides of the shoe and constructed to present an 40 abutment to be engaged and operated by relative movement of the shoe support and the wiper support to swing the wipers inwardly over the shoe about said axes.

165. In a machine of the class described, 45 a shoe support and a wiper support mounted for relative movement in a direction lengthwise of the shoe, end embracing wipers mounted on said wiper support for swinging movement laterally of the shoe 50 about different axes laterally displaced from the longitudinal median line of the shoe, and a device connected to said wipers and constructed to present an abutment to be engaged and operated by relative movement of the shoe support and the wiper support to swing the wipers inwardly over the shoe about said axes, said abutment being

adjustable to time variably the beginning of the swinging movement of the wipers.

166. In a machine of the class described, 60 a shoe support and a wiper support mounted for relative movement in a direction lengthwise of the shoe, end embracing wipers constructed to extend substantially continuously round the end and along the opposite sides of the end portion of the shoe, 65 said wipers being mounted on the wiper support for swinging movement laterally of the shoe, means for holding the wipers normally in an open position laterally of the 70 shoe to cause them to wipe the upper over the extreme end of the shoe prior to their lateral closing movement, and a device connected to the wipers and arranged to be operated by the relative movement of the 75 shoe support and the wiper support after the wipers have wiped the upper over the end of the shoe to swing them inward laterally of the shoe.

167. In a machine of the class described, 80 end embracing wipers mounted for swinging movement laterally of a shoe about different axes laterally displaced from the longitudinal median line of the shoe, a shoe support movable to carry a shoe lengthwise into 85 operative relation to said wipers, a device connected to the wipers and arranged to be operated by said movement of the shoe support to close the wipers inward laterally of the shoe about said axes, and means for adjustably limiting the movement of said device to determine the extent of overwiping movement of the wipers.

168. In a machine of the class described, 90 end embracing wipers mounted for swinging movement laterally of a shoe about different axes laterally displaced from the longitudinal median line of the shoe, a shoe support movable to carry a shoe lengthwise into 95 operative relation to said wipers, a device connected to the wipers and having an abutment to be engaged and operated by movement of the shoe support to close the wipers inward laterally of the shoe, means for holding the wipers normally open to cause them to overwipe the upper at the extreme end of the shoe before said abutment is engaged and operated, and a stop for said device adjustable to vary the extent of lateral closing movement of the wipers.

In testimony whereof I have signed my name to this specification.

EUGENE L. KEYES.
